CENTRALIZED TRAFFIC CONTROLLING
SYSTEM FOR RAILROADSNeil D. Preston, Rochester, N. Y., assignor to
General Railway Signal Company, Rochester,
N. Y.Application December 29, 1932, Serial No. 649,369
Renewed November 21, 1935

17 Claims. (Cl. 177—353)

This invention relates to centralized traffic controlling systems for railroads, and more particularly to the communication part of such systems.

- 5 The system of the present invention is to be considered an improvement on my earlier filed copending applications Ser. No. 589,186, filed January 27, 1932, and Ser. No. 644,481, filed November 26, 1932.
- 10 In railroad traffic controlling systems, the traffic is controlled from a control office usually located at a central point with respect to outlying field stations, which are connected to the control office by means of the communication system. Likewise, the location of trains and the condition of the traffic controlling devices at remote locations or outlying field stations are indicated to the attendant at the control office. The location of trains and the condition of the traffic controlling devices are transmitted to the control office by means of the communication part of the system. This invention is particularly useful in such a system which is called upon to carry out a large number of controls and indications during a very short time. A single dispatcher can handle the traffic over a large section of track so that it is desirable that the code combinations be capable of transmission at such a high rate of speed that the accumulation of 30 stored controls and indications is avoided.

The switches and signals are distributed throughout the territory and those located relatively near or adjacent each other, together with the apparatus provided to govern these switches and signals, are conveniently referred to as comprising a field station. The communication system is provided to interconnect the control office with the several field stations and is so organized that complete control and supervision 40 of the various switch and signal devices at the remote stations are obtained by the operator. Such a traffic controlling system is supplemented by the well known automatic block signal system and other local means ordinarily provided to 45 guard against unsafe train movements, improper operation of track switches or the like.

In accordance with the present invention, the communication system comprises three line wires extending from the control office through 50 the several field stations in series. These three line conductors are referred to in this disclosure as the S line, which is the stepping line and the A and B lines, which are the return conductors. The S line, in addition to being used for controlling the stepping operations, is used in com-

bination with the A and B lines for the transmission of controls from the control office to the field stations. The S line, likewise, cooperates with the A and B lines in connection with the transmission of indications from the field stations to the control office.

The S line and the A and B lines are connected together at the last field station of the series and the circuits are so organized that current which is applied to the S line at the control office 10 extends through the several field stations in series and at the last field station, a return path is completed by way of the A and B lines. The arrangement is such that any field station in the series may control the circuits in a manner 15 that the return path to the control office may be by way of one or the other or both the A and B line conductors.

In accordance with the present invention, it is proposed to use the three line wires for transmitting codes for selecting one particular field station at a time and actuating controlling devices thereat. Likewise, these three line conductors are used for transmitting codes for registering one particular field station at a time in the 25 control office and thereafter actuating certain indication devices at the control office associated with the registered field station.

The system is of the coded simplex type and is operated through cycles during each of which 30 either the transmission of controls or the transmission of indications can occur. The communication system is used for the transmission of controls and indications in such a way that, irrespective of the number of stored controls in 35 the control office awaiting transmission to field stations, a field station may be registered in the control office and cause the next succeeding operating cycle to be an indication cycle. If several controls for transmission from the control 40 office to field stations are stored and several indications for transmission from field stations to the control office are stored at the same time, the system operates in such a way that controls and indications will be transmitted during al- 45 ternate cycles.

For the transmission of controls, a predetermined number of impulses of selected polarities is placed on the line circuit for operating the apparatus at the control office and at the field 50 stations through a cycle of operations, irrespective of the character of the impulses. The distinctive character of these impulses in part determines the particular station to be selected and the controls to be transmitted to the selected sta- 55

tion. In addition to the character of the impulses applied to the S line, the circuits are so organized that the return path from the field stations may be by way of both the A and B line conductors in 5 multiple or the B line conductor alone. This provides means in addition to the polar impulses for the transmission of controls so that a choice of four code combinations is obtained for each step.

- 10 For the transmission of indications, means are provided to condition the A and B lines during a portion of each energized period of the S line for creating two code characters, either one of which may be selected. During another portion of each 15 energized period of the S line, the A and B line wires are again conditioned to provide a choice of three code characters, any one of which may be selected. Therefore, a choice of five code characters for each step is obtained during each energized period of the S line circuit. The energized periods of the S line circuit will be referred to as the "on" periods, while the deenergized periods of the line circuit will be referred to as the "off" periods.
- 20 One feature of the present invention relates to the manner in which indications are preconditioned during the "off" periods, for obtaining a choice of two code characters and conditioned during the "on" periods for obtaining an additional choice of three code characters, with the chosen indications executed during a portion of an "on" period and a portion of the next succeeding "off" period.

In the present embodiment, with the S line 35 energized at the start of an "on" period, the A or B line may be energized, resulting in two distinctive conditions. With the S line energized later during the same "on" period, the return circuit may be by way of the A line alone, the B line alone or the A and B lines in multiple, thus giving 40 three more distinctive conditions, thus resulting in five separate and distinct conditions or code combinations for each step for the transmission of indications.

Another feature of the present invention relates to the manner in which controls are conditioned during the "off" periods, for obtaining a choice of four code combinations and the manner in which the chosen controls are executed during the next succeeding "on" period. Obviously, the provision of four distinctive code combinations for each step results in obtaining sixteen distinctive codes where each complete code comprises two steps. Similarly, sixty-four distinctive complete codes are obtained where each complete code comprises three steps. In other words, the number of code combinations for the transmission of controls is equal to four raised to the power of the number of steps. This is accomplished by energizing the line circuits with current of different polarities and providing the return path by way of both return conductors in multiple or one return conductor alone.

Obviously, the provision of five distinctive code 65 characters per step for the transmission of indications results in obtaining twenty-five distinctive codes where each complete code comprises two steps. In this connection, the number of code combinations obtained is equal to five raised to the power of the number of steps and this is accomplished by energizing the line circuits with current of the same polarity for each distinctive code.

Therefore, one purpose of the present invention 75 is to provide a code type selector system

which builds up rapidly as the number of steps increases and to accomplish this over a minimum number of line wires.

Other objects and advantages of the present invention will be hereinafter set forth in the 5 specification and claims and further details will be better understood by referring to the accompanying drawings, which illustrate one method of carrying out the invention by way of example.

The drawings illustrate in a diagrammatic 10 manner the apparatus and circuits employed and for convenience in describing the invention in detail, those parts having similar features and functions are designated in the different figures by like reference characters, generally made distinctive either by the use of distinctive exponents 15 representative of their location or by the use of suitable preceding numerals representative of the order of their operation, and in which:

Fig. 1 diagrammatically shows the line circuits 20 illustrated in Figs. 2A, 2B, 2C, 2D and 3.

Figs. 2A, 2B, 2C and 2D illustrate the apparatus and circuits employed at the control office;

Fig. 3 illustrates the circuits employed at one 25 of the field stations;

Fig. 4 illustrates an operation chart which will be conveniently referred to during the following description for obtaining a concentrated picture of the sequence of operations of the system during control and indication cycles;

Fig. 5 shows a modification of the line circuits.

To simplify the line circuit schematic, Fig. 1 shows the line condition after a cycle is started, rather than its normal at-rest condition.

When tracing the circuits, Figs. 2A and 2B 35 should be placed together in the order named, Figs. 2C and 2D should be placed together in the order named and below Figs. 2A and 2B with correspondingly numbered lines in alignment.

General description

The three-wire line circuit which connects the control office with the field stations is shown in heavy lines. Fig. 1 indicates, in schematic form, the three line conductors and shows the S line 45 with battery connected to it from battery B, through the windings of relay F in the control office and relays F¹, F², F³ etc. at the field stations. At the last field station of the series, the S line is connected through resistance coils R¹ and 50 R² to the A and B lines respectively. In series with the A line at the stations are A line relays FA¹, FA², FA³, etc., as well as contacts of the A line impulsive relays at the stations, such as PLA¹, PLA², PLA³, etc.

The embodiment shown in Figs. 2A, 2B, 2C, and 2D does not have resistance coils RS¹, RS², RS³, etc., nor the contacts shown in connection with relays SO¹, SO², SO³, etc., of Fig. 5 so that the A line conductor at the different stations is 60 in series with only the A line relays and the contacts of the A line pulsing relays. The B line conductor is in series with the B line impulsive contacts such as PLB¹, PLB², PLB³, etc., while both the A and B line conductors are connected 65 in series with A and B line message relays MA and MB, respectively, in the control office. Contacts of relay PCA in the control office are used to open and close the A line in a manner and for a purpose which will be specifically pointed out 70 in detail.

The dotted rectangle in the upper right hand portion of Fig. 3 shows the extension of the S line through line relays of other field stations and the connection to the A and B return conductors 75

through resistance coils at the last station and contacts of the A and B line impulsing relays at other stations.

It will be understood that stations in addition to the one shown in Fig. 3 have apparatus and circuit arrangements practically the same as that illustrated. As will be more specifically pointed out in the following description, the points of difference in the circuit connections at different field stations are the distinctive connections of the code jumpers for conditioning the circuits so that a particular field station will be fully responsive only to the particular code assigned to that station.

The symbols (+) and (−) indicate the positive and negative terminals respectively of suitable batteries or other sources of current and the circuits connected to these symbols always have current flowing in the same direction. The symbols (B+) and (B−) indicate the positive and negative terminals respectively, of a battery or other source of current having an intermediate tap (CN) and the circuits connected to these symbols may have current flowing in one direction or the other, depending upon whether the circuit connected to terminal (B+) or (B−) is completed to the intermediate tap (CN).

No attempt has been made to show all of the apparatus employed, such as the total number of manual controlling devices at the control office, the total amount of equipment or its exact arrangement at the field station, since this apparatus and equipment may vary in extent to suit local conditions. The character of the apparatus illustrated in the typical control office and the typical field station will now be considered.

Control office equipment.—As typical of the equipment located in the control office, a control machine having a group of control levers for each field station connected to the line circuit is provided. A miniature track switch *ts* corresponds to a particular track switch in the field and represents the actual track layout at the field location. Various indicating lamps or equivalent devices are likewise provided, with apparatus and circuit connections arranged to control these indicating devices as required.

The equipment for one track switch comprises a switch machine lever SML, a signal lever SGL, a self restoring starting button SB, a miniature track switch *ts* and the indication lamp OS. Similarly, additional control levers (not shown) may be associated with a single field station, but in order to simplify the drawings and description, these devices have been omitted. Additional indicating devices, such as signal lamp OS, may likewise be provided but they have not been shown in this embodiment for the sake of simplicity. The selection of the field station illustrated in Fig. 3 by means of starting button SB of Fig. 2A and thereafter the control of a track switch TS¹, (Fig. 3), by means of a lever SML (Fig. 2A) may be considered as typical of the selection of other field stations and the control of other traffic controlling devices. Likewise, the registration of a field station by means of an automatic start from the field and thereafter the transmission of indications from track relay T¹ (Fig. 3) may be considered as typical of the registration of other field stations and the transmission of other indications.

The actuation of the lever SML to one extreme position or the other, followed by the depression of the starting button SB, results in the normal or reverse operation of the track switch corre-

sponding to lever SML at that field station which is associated with starting button SB and this operation is controlled through the medium of the communication system of the present invention. The momentary depression of the starting button is preferably stored by a storing relay (not shown) which in turn picks up the corresponding code determining relay CD of the associated station. The starting button SB is shown connected to relay CD by means of a dotted line instead of the complete circuit connections, in order to simplify the present disclosure.

The storing relays associated with the starting buttons and their corresponding CD relays are so interconnected that only one CD relay may be up during one cycle of operations, irrespective of the number of storing relays which are simultaneously energized or energized in rapid succession. This interconnection of the CD relay circuits is so arranged that if several storing relays are up at the same time, the corresponding CD relays will be picked up one at a time during successive operating cycles, in an order predetermined by their relative locations in the relay bank, all of which has been completely disclosed in the prior application of N. D. Preston et al., Ser. No. 455,304, filed May 24, 1930.

The control office includes a selecting relay SEL which responds to the polarity of the conditioning impulse applied to the S line. This relay is picked up at the start of an indication cycle, remains up until the end of the indication cycle and stays down during a control cycle. Its function is to select the control and indication circuits during control and indication cycles. A control office start relay C is picked up when a cycle of operations is initiated from the control office and a field start relay FC is picked up when a cycle of operations is initiated from a field station. Either relay C or relay FC when picked up, is stuck up through back contacts on an extra stepping relay LV in combination with contacts on relay SEL, so that relay C will drop at the end of a control cycle while relay FC will be held up. If relay FC is up, relay C cannot pick up.

The circuit connections of relays C and FC are such that when indications and controls are stored in both the field and the control office, the control office has the preference in obtaining control of the line circuit so that the first cycle will be a control cycle. The next cycle will be an indication cycle and if several controls and indications are simultaneously stored, the communication system will be used alternately for controls and indications.

Line relay F and line repeating relay FP are used to control the stepping and selecting operations. Slow acting line repeating relays SA and SAP are picked up at the beginning of each cycle and dropped during the "change to normal" period at the end of the cycle. These two relays have such slow acting characteristics that the pick-up time of each is relatively long compared with the pick-up time of relays such as F and FP. The pick-up time of these slow acting relays is relatively short in comparison with the time required for their release after they are de-energized by the removal of current from their windings. The releasing or drop-away time of relay SA is sufficiently long so that its contacts remain in their actuated positions during all "off" periods between successive impulses of a cycle, but these contacts are restored to normal during the last "off" period, which is comparatively long

for the purpose of returning the system to the normal period of rest or the period of blank.

Associated with line relay F and its repeating relays is a bank of stepping relays 1V, 2V, 3V and LV together with a half step or steering relay VP, which are provided to mark off the successive steps of each cycle. Steering relay VP serves the purpose of steering the impulses from relay FP to the proper stepping relay and for steering the executing circuits to the proper selecting contacts of the stepping relays, all at the proper time. An impulsive relay E is jointly controlled by the stepping relays and the steering relay. The pick-up and drop-away operations of relay E are repeated by relay EP which governs the opening and closing of the S line conductor.

Relay E, in addition to controlling the line pulsing relay EP, jointly controls with relay FP, the stick circuit of relay MX. Relay E also controls the stick circuit of relays MAP and MBP as well as controlling the circuits over which the indications are executed, all of which will be specifically pointed out in the detailed description. Relay MA is controlled over the A line conductor, relay MB is controlled over the B line conductor and their respective repeating relays MAP and MBP control the selection of a choice of five indication code combinations during the "on" period of each step. Relay MX is jointly controlled by relays MAP and MBP to record the choice of two of these indication code combinations during the first part of the "on" period of each step. Relays MAP and MBP thereafter record the choice of three of these combinations during a succeeding part of the "on" period of each step.

The polarity of the impulses applied to the line circuit from a battery B is determined by positive code sending relay PC and negative code sending relay NC. These two relays are controlled on steps of a control cycle in accordance with the station code and the controls to be transmitted for that particular cycle. A line conditioning relay PCA is provided for energizing or de-energizing the A line conductor during the transmission of control impulses. Relays PC, NC and PCA in combination provide a choice of four distinctive control code combinations for each step. A starting relay STR is picked up to initiate a cycle of operations, both when controls are to be transmitted due to the manual initiation of the cycle in the control office and when indications are to be transmitted due to the automatic initiation of a cycle by a field station.

For the purpose of illustrating station registration, a typical pilot relay arrangement is shown in Fig. 2C. The pilot relays 1PT, 2PT and 3PT are connected to the indication buses so that they may be positioned on the first step of a cycle when indications are transmitted. Additional pilot relays may be provided for additional steps, up to the point where sufficient codes for station registration are obtained. These pilot relays are indicated as being of the two-position polarized magnetic stick type, although it should be understood that any other suitable type or arrangement may be provided for accomplishing the result obtained by this typical arrangement.

A station relay ST (Fig. 2C) provides for the registration in the control office of the station which is transmitting indications. This relay is merely typical of a number of such relays which would ordinarily be provided, one for registering each individual station. The other relays,

similar to relay ST, would be connected to the conductors 2 to 6 inclusive shown associated with bracket STN. Suitable indication storing relays, such as IR¹, are provided for storing the various indications transmitted from the field stations, after a station has been registered in the control office by the selection of a relay similar to ST. The indication storing relay IR¹ is controlled in accordance with the occupied or unoccupied condition of the detector track section associated with the outlying track switch, illustrated in Fig. 3, as repeated by a track relay T¹, so that indicating lamp OS is controlled by the passage of a train to visually indicate to the dispatcher the occupied or unoccupied condition of the section of track. It will be understood that relay IR¹ is merely typical of additional indication storing relays which may be provided for storing additional indications repeated by other conditions at the field stations, such as the positions of switch machines, signals, etc.

Field station equipment.—The field station illustrated in Fig. 3 includes, besides the apparatus already mentioned, a quick acting line relay F¹ and a quick acting line repeating relay FP¹ which repeat the energizations and deenergizations of the S line circuit. Relay FP¹ repeats the impulses in the S line circuit irrespective of their polarities while relay F¹ is actuated to the right by a positive impulse and to the left by a negative impulse applied to the line from battery B in the control office.

A slow acting relay SA¹ of the neutral type repeats the energized condition of relay FP¹, having such characteristics that its pick-up period is long compared with the pick-up period of a fast acting relay such as FP¹. The releasing period of relay SA¹ is relatively long compared with its pick-up period, so that its contacts remain in their picked up positions between the successive energizations of relay FP¹. Relay SA¹ may be said to define the bounds of each operating cycle, since it is picked up at the beginning of each cycle, remains energized during the transmitting period and releases during the "change to normal" period at the end of the cycle.

The field station includes a bank of stepping relays 1V¹, 2V¹, 3V¹ and LV¹ together with the associated steering or half step relay VP¹, operating in a similar manner and in synchronism with the stepping relay bank in the control office. Steering relay VP¹ steers the impulses from relay FP¹ to the proper stepping relay, as well as steering the connections from the windings of the line impulsive relays PLA¹ and PLB¹ to the proper indication buses, all at the proper time.

The line impulsive relays PLA¹ and PLB¹ function to open the A and B lines respectively, to provide code combinations during the transmission of indications. These two relays are conditioned in accordance with the condition of the indication buses shown in the lower right hand portion of Fig. 3. Relay VPC¹ exercises a control over the steering relay VP¹ in such a way that relay VP¹ cannot shift until the line impulsive relays PLA¹ and PLB¹ are in their normal or deenergized positions during the "on" periods.

A change repeating relay CHP¹ is provided to register a change in the traffic controlling devices at the station, so that the system will be automatically started through a cycle of operations for the transmission of new indications whenever this relay is down. Although the circuit of relay CHP¹ is not shown in detail, it will be understood that it is normally stuck up and is released to

close its back contact 157, by the interruption of its holding stick circuit (not shown), when a change in position of a track relay T^1 or any other suitable relay takes place. Relay CHP^1 will 5 register a change in one or more of a large number of devices and initiates indication cycles as long as there are new indications to be transmitted.

A lock-out relay LO^1 located at each field station, determines when a particular station is to 10 transmit new indications. This relay is picked up during the initiating period of an indication cycle and is stuck up until the "change to normal" period at the end of the cycle. The lock-out relay supplies (—) potential to the A and 15 B line impulsive relays PLA^1 and PLB^1 as long as the station relay SO^1 is down, so that these line impulsive relays receive current during an indication cycle only at the station transmitting indications.

20 A station selecting relay SO^1 is provided at each field station and picks up at all stations during the conditioning period of a control cycle. These station selecting relays are dropped out at various stations during the transmitting period of 25 a cycle, so that only the one associated with the desired station remains actuated after the transmission of the station selecting code. Relays LO^1 and SO^1 control the circuits to the stepping relays so that stepping is not effected at those stations not in connection with the communication circuit.

An additional line relay FA^1 is included in the A line circuit and is used in cooperation with 30 line relay F^1 for repeating the code combinations transmitted during a control cycle, for performing 35 selective and control functions as will be specifically pointed out in detail. Resistance units R^1 and R^2 , illustrated within the dotted rectangle in the right hand portion of Fig. 3, are inserted in the A and B line conductors at the last 40 station of the series to provide a drop in potential for picking up a lockout relay, similar to relay LO^1 during the initiating period of an indication cycle.

45 A track switch TS^1 is operated by a switch machine SM^1 of any suitable type, such for example, as disclosed in the patent to W. K. Howe, 1,466,903 dated September 4, 1923. The position, locked and unlocked conditions of the track switch 50 are repeated by the usual switch repeating relay (not shown). The track switch has associated with it the usual detector track section, having a track battery and a track relay T^1 , as well as suitable approach locking and detector locking means to govern the safe operation of the track switch, in 55 accordance with traffic conditions.

A change in the condition of the detector track section is repeated by relay T^1 and the circuits used for transmitting the condition of relay T^1 have been shown in detail. The indication code 60 circuits which are connected to contacts of relay T^1 may be considered typical of the manner in which other indication code circuits are connected to other relays, such as the relay which responds to the operation of the track switch.

65 It is believed that the nature of the invention, its advantages and characteristic features may be best understood by continuing the description in a manner relating to the operation of the system.

70 General operation

The circuits are shown in the normal or condition of rest, from which the system may be initiated into a cycle of operations by a manual operation at the control office or an automatic 75

operation at any one of the field stations, whenever there are new controls or new indications, respectively, to be transmitted.

Irrespective of whether a cycle is for the transmission of controls or the transmission of indications, a predetermined number of impulses is applied to the line circuit to cause the stepping relays at the control office and at the field stations to operate in synchronism. These impulses are of comparatively short duration, the de-energized 10 or "off" periods of the stepping line circuit being comparatively shorter than the energized or "on" periods, except the last "off" period which is sufficiently long to allow the slow releasing relays to release for restoring the system to normal. 15

When a cycle of operations is initiated for the transmission of controls, the character of the impulses applied to the stepping line and the condition of the A line return conductor are determined by the particular station to be selected and 20 the particular controls to be transmitted to the selected station, in accordance with the code jumper connections and the positions of the control levers, respectively, for that station.

During the transmission of controls, the A and 25 B line conductors are energized in multiple and in series with the S line conductor at each step under certain conditions and under other conditions the B line conductor alone is energized in series with the S line conductor at each step. 30 During the transmission of controls, an initiating (+) impulse is applied to the S line conductor for picking up all the station relays similar to relay SO^1 of Fig. 3.

When a cycle of operations is initiated for the 35 transmission of indications, the character of all impulses applied to the stepping line is the same, with the A and B lines conditioned as determined by the indications to be transmitted from the field station. The initiating impulse applied to the stepping line is (—), which is effective to prevent picking up any station relay similar to SO^1 of Fig. 3. Since the line circuit is energized with a series of (—) impulses during such a cycle and since the cycle starts out with no station relays similar to SO^1 picked up, the (—) impulses which 45 follow the initiating impulse are ineffective to select a station or actuate a control device at a station.

The A and B line conductors are normally energized, the stepping line conductor S is normally 50 deenergized and when controls or indications are initiated, the battery connection in the control office is switched so that temporarily the S line is energized, the return circuit being by way of both the A and B lines, for the transmission of 55 controls and by way of the B line alone for the transmission of indications.

This period during which the battery is switched from the A and B line conductors to include the S line is conveniently referred to as the conditioning period at the start of a control cycle and the initiating period at the start of an indication cycle. Immediately following the conditioning or initiating period is the lock-out period, effective during an indication cycle to so condition the circuits that only one station may transmit indications at the same time.

After the conditioning and lock-out periods, the system continues through a complete cycle of operations, consisting of a number of "off" and 70 "on" periods, this number being determined by the number of steps required and the number of steps in turn being governed by the size of the system. After the last "on" period, a comparatively long "off" or de-energized period is pro- 75

vided to condition the relays for changing to normal or the period of blank. After this change to normal period, the A and B line conductors are again energized by current from battery B, which restores the system to the normal period.

For convenience in describing the operation of the present invention, an operation chart is shown in Fig. 4. In the upper portion of this chart, the important functions during a control cycle are illustrated, while the lower portion illustrates the important operations of an indication cycle. Referring to the control cycle, the normal period is shown at the extreme left and during this period line S is de-energized or open as indicated by reference character O. Line A is energized with (+) potential and line B with (-) potential as indicated. It is during this period that the system is manually started from the control office. The normal period is an "off" period since line S is de-energized.

During the next or conditioning "on" period, line S is energized with (+) potential and the return circuit by way of lines A and B is to (-) potential, as indicated by these reference characters. It is during this "on" period that all relays similar to relay SO¹ of Fig. 3 are picked up.

From the beginning of the conditioning period to the end of the cycle is referred to as the operating cycle. From the beginning of the first "off" period to the end of the third "on" period is referred to as the transmitting period. The transmitting period is divided into "off" and "on" periods with only three steps indicated, namely, the first, second and third "off" and "on." It will be understood that additional steps are inserted between the third "on" and the "change to normal" periods when the size of the system increases.

In the indication cycle chart of Fig. 4 a normal period is shown which is the same as the control cycle normal period, except it is noted that this cycle is started automatically from the field. This is followed by an operating cycle divided into initiating, lock-out, conditioning, transmitting and "change to normal" periods. The conditions of the line conductors during these different periods and certain important relay operations are set forth in the different columns of this chart. The transmitting period, in addition to being divided into "off" and "on" periods, has these periods subdivided as indicated, the purpose of which will be specifically described.

Detailed operation

Normal period.—Relays MA and MB are normally energized by current flowing over the A and B lines in series and extending from the (+) terminal of battery B, back contact 10 of relay STR, back contact 15 of relay PCA, conductor 16, winding of relay MA, A line conductor 11, back contact 150 of relay PLA¹, winding of relay FA¹, conductor 151, through contacts such as PLA² and windings of relays such as FA² at other field stations, resistance coils R¹ and R² in series at the last field station, back contacts such as PLB² at other field stations, conductor 152, back contact 153 of relay PLB¹, B line conductor 12, winding of relay MB, conductor 124 and back contact 13 of relay STR to the (-) terminal of battery B. Relay MAP is normally energized over a circuit extending from (+), front contact 128 of relay MA and lower winding of relay MAP, to (-). Relay MBP is normally energized over a circuit extending from (+), front contact 129 of relay MB and lower winding of relay MBP, to

(-). All other relays in the control office are normally de-energized.

In pointing out the relays which are normally energized at the field stations, it will be understood that relays similar to those shown in Fig. 3 are normally picked up by means of circuits described in connection with this figure. Relay VPC¹ is normally energized over a circuit extending from (+), back contact 190 of relay PLA¹, back contact 195 of relay PLB¹ and winding 10 of relay VPC¹, to (-).

Change repeating relay CHP¹ and track relay T¹ are normally picked up over circuits (not shown), but obvious to those skilled in the art. Relay FA¹, connected in A line conductor 151, and which is in series with the A and B line conductor circuit above described, is normally picked up. All other relays shown in Fig. 3 are in their normal or de-energized conditions.

Manual starting.—With the system in its normal condition it will be assumed that the operator in the control office desires to send controls to a particular field station, such as the one illustrated in Fig. 3. It will be assumed that the complete code associated with this station is (+) 25 (+) (-) (-) and that it is transmitted during two "off" and "on" periods, marked off by the operation of the first two stepping relays. The code jumper connections at the control office and at the field station have been shown connected 30 in accordance with this particular distinctive code. It will also be assumed that the distinctive code sent out from the control office during the third step is (+) (-), determined by the positions of levers SML and SGL. 35

When the starting button SB is actuated, a suitable storing relay is operated and its associated CD relay, which corresponds to the station associated with button SB, is picked up. When relay CD picks up, it closes a circuit for picking up relay C which extends from (+), back contact 16 of relay SA, conductor 136, front contact 17 of relay CD, conductor 137, back contact 23 of relay FC and winding of relay C, to (-). Relay C closes a stick circuit for itself extending 45 from (+), back contact 24 of relay LV, conductor 138, front contact 68 and winding of relay C, to (-).

The operation of relay C opens, at its back contact 74, the direct circuit to relay NC so that the operating circuit for relay NC is by way of the code jumper connections alone. Relay C closes a circuit for picking up relay STR which extends from (+), back contact 32 of relay SAP, front contact 18 of relay C and winding of relay 55 STR, to (-). Relay C also closes a circuit for picking up relay PC which extends from (+), back contacts 19, 20 and 21 in series of stepping relays 3V, 2V and 1V respectively, conductor 139, front contact 22 of relay C and lower winding of relay PC, to (-).

This is the conditioning period. The picking up of relays STR and PC energize the line conductors by means of a circuit extending from the (+) terminal of battery B, front contact 10 of relay STR, front contact 25 of relay PC, back contact 26 of relay NC, winding of relay F, back contact 27 of relay EP, S line conductor 28, winding of relay F¹ of the field station shown in Fig. 3, windings of other line relays similar to F² located at other field stations, resistance coil R¹ at the last field station, windings of relays such as FA² at other field stations, back contacts such as PLA² at other field stations, conductor 151, winding of relay FA¹, back contact 150 of relay PLA¹, 75

A line conductor 11, winding of relay MA, conductor 76, back contact 15 of relay PCA, front contact 13 of relay STR, back contact 7 of relay NC and front contact 8 of relay PC to the (—) terminal of battery B. This circuit branches off at the last field station and also extends through resistance coil R², back contacts similar to PLB² at other field stations, conductor 152, back contact 153 of relay PLB¹, B line conductor 12, winding of relay MB, conductor 124, back contact 7 of relay NC and front contact 8 of relay PC to the (—) terminal of battery B.

The above described circuit energizes line S with a (+) potential and lines A and B in multiple with a (—) potential, as indicated under the conditioning period in the operation chart of Fig. 4. This current actuates relays F, F¹ and other relays such as F² to the right. Relays such as FA², relay FA¹, relay MA and relay MB remain in their actuated positions. Relay F closes a circuit for picking up relay FP which extends from (+), contact 29 of relay F in its right hand position and winding of relay FP, to (—). Relay F¹ closes a circuit for picking up relay FP¹ which extends from (+), contact 154 of relay F¹ in its right hand position and winding of relay FP¹, to (—).

The actuation of relay FP in the control office closes a circuit for picking up relay SA which extends from (+), front contact 30 of relay FP and winding of relay SA, to (—). Relay SA closes a circuit for picking up relay SAP extending from (+), front contact 31 of relay SA and winding of relay SAP, to (—).

At the field station, a circuit is closed for picking up relay SO¹ which extends from (+), back contact 158 of relay SA¹, back contacts 161, 162 and 163 of relays 3V¹, 2V¹ and 1V¹ respectively, contact 160 of relay F¹ in its right hand position and winding of relay SO¹, to (—). It will be understood that a similar circuit is effective at other field stations for picking up other relays similar to SO¹.

The actuation of relay FP¹ closes a circuit for picking up relay SA¹ which extends from (+), front contact 155 of relay FP¹ and winding of relay SA¹, to (—). The operation of relay SA¹ interrupts the above described pick-up circuit of relay SO¹ but it is not released, since a holding stick circuit is closed extending from (+), front contact 171 of relay SO¹, back contacts 161, 162 and 163 of relays 3V¹, 2V¹ and 1V¹, contact 160 of relay F¹ in its right hand position and winding of relay SO¹, to (—).

Referring back to the control office, the actuation of relay SA closes a stick circuit for holding relay STR in its picked up position until the end of the cycle, which circuit extends from (+), front contact 16 of relay SA, front contact 38 of relay STR and winding of relay STR, to (—). This stick circuit is closed before the pick-up circuit of relay STR is opened at back contact 32 of relay SAP. Relay SAP opens, at its back contact 69, the pick-up circuit of relay FC so that this latter relay can not pick up to register a field station start until the system is advanced into its normal period by the release of relay SAP.

Relay SAP closes a circuit for picking up relay EP which extends from (+), front contact 32 of relay SAP, back contact 33 of relay E and lower winding of relay EP, to (—). The purpose of front contact 91 of relay EP is to short circuit the upper winding of this relay after it is picked up, which has the effect of rendering it quick to

pick up and slow to release, which is desired for the proper timing of the stepping operation. The actuation of relay EP opens the S line conductor at its back contact 27, which is effective to de-energize the line circuits and advance the system into the first "off" period.

Polarity selection of impulses.—As above pointed out, the first impulse in line S is (+) when a cycle of operations is started from the control office and is due to the fact that (+) control relay PC is picked up at the start of a control cycle. This impulse, in addition to the above mentioned operations, fixes this cycle as a control cycle by preventing the picking up of relay SEL of Fig. 2B, because contact 39 of relay F is not closed before back contact 31 of relay SA is opened.

With line S de-energized and the system in its first "off" period, relays F, F¹ and others such as F² are released. Relay F causes the release of relay FP by opening its contact 29. As will be specifically pointed out later on in the description, stepping relay IV is picked up during the first "off" period. The No. 1 control is conditioned by selecting the polarity, during the first "off" period, to be applied to line S during the first "on" period. Assuming that relay IV is up, a circuit is effective for energizing relay PC which extends from (+), back contact 40 of relay SEL, conductor 140, back contact 35 of relay 3V, back contact 36 of relay 2V, front contact 31 of relay IV, No. 1 code bus 44, front contact 45 of relay CD, code jumper 46, (+) bus 47 and lower winding of relay PC, to (—). This connection of code jumper 46 to (+) bus 47 selectively conditions the first part of the first control impulse (+). If code jumper 46 were connected to (—) bus 42, then relay NC would be picked up instead of relay PC, thus providing a (—) impulse for the first part of the No. 1 control.

The second part of the No. 1 control is determined by the condition of relay PCA and in the embodiment disclosed it is assumed that relay PCA is down during the first "off" period. This results in both lines A and B becoming energized in series with the S line during the first "on" period, because contact 15 remains closed.

If code jumper 46 is connected to the second terminal from the bottom leading to code bus 41, relays PC and PCA are both picked up in series, the circuit extending through the upper winding of relay PC from bus 41 and the lower winding of relay PCA, to (—). This provides a (+) impulse on the S line for the first part of the No. 1 control code because relay PC is up. Relay PCA up establishes the return circuit by way of the B line conductor alone, since back contact 15 is open, which opens conductor 76 leading to the A line conductor 11.

With the A line conductor energized (when code jumper 46 is connected to the lower terminal leading to bus 47), relay FA¹ at the field station picks up. The energized condition of the A line conductor is conveniently referred to as a (+) code and is indicated thus in the second part of the code in the first "off" and "on" periods of the control cycle shown in Fig. 4. If the A line conductor is de-energized, then relay FA¹ is down and this is conveniently referred to as a (—) code combination.

It will thus be seen that four distinctive combinations are obtained during each step when controls are transmitted. These are: First, (+) (+) with jumper 46 connected as shown in Fig. 2A, which results in relay PC being up, relay NC be-

ing down and relay PCA being down. This results in energizing line S (+) and energizing line A for picking up relay FA¹. Second, a (+) (-) combination is obtained when code jumper 46 connects to the second terminal from the bottom leading to bus 41, because relays PC and PCA pick up. Relay PC energizes line S (+) and relay PCA de-energizes line A, which is conveniently referred to as (-). Third, a (-) (+) combination is obtained when jumper 46 is connected to the third terminal from the bottom, which leads to bus 42 and is effective to pick up relay NC alone. Relay NC energizes line S (-) and since relay PCA remains down, relay FA¹ picks up which is referred to as (+). Fourth, a (-) (-) combination is obtained when jumper 46 is connected to the fourth terminal from the bottom leading to bus 71, since this results in picking up relays NC and PCA in series. Relay NC energizes line S (-) and relay PCA opens the A line conductor so that relay FA¹ remains down which is referred to as (-).

The control of the PC, NC and PCA relays is similar during other "off" periods by means of other code jumper connections such as 67. Thus, in the second "off" period relays 2V and VP will be up and the selection of the (+) or (-) combinations by means of jumper 67 selectively connected to one of the bus wires 47, 41, 42 or 71, is extended by way of front contact 111 of relay CD, No. 2 code bus 112, front contact 36 of relay 2V, back contact 35 of relay 3V, conductor 140 and back contact 40 of relay SEL, to (+). In the present embodiment, it is assumed that the second step (No. 2) code jumper 67 connects to bus 71, so that relays NC and PCA will be up during the second "off" period. With relays NC and PCA up and relay PC down, the code combination is (-) (-) as above explained and as is indicated in Fig. 4.

During the third "off" period, it will be assumed that relay 3V is up, as indicated in the operation chart. The No. 3 control is conditioned during this period by extending the circuit from (+), back contact 40 of relay SEL, conductor 140, front contact 35 of relay 3V, No. 3 code bus 114, front contact 115 of relay CD, contact 43 of lever SML in its right hand position, bus 41 and lower winding of relay PC, to (-). This determines the first part of the No. 3 control (+). The second part of the No. 3 control is (-), determined by picking up relay PCA over a circuit which extends from (+), back contact 116 of relay SEL, conductor 141, front contact 117 of relay 3V, front contact 118 of relay CD, contact 119 of lever SGL in its right hand position, bus 125 and upper winding of relay PCA, to (-).

It will be apparent that a (-) impulse would be conditioned for the first part of the No. 3 control if lever SML should be in its left hand position, because this would extend the first part of the above traced circuit through contact 43 of lever SML in its left hand position to bus 42, which would be effective to energize relay NC. Likewise, if lever SGL were in its alternate position, contact 119 would be open so that bus 125 would be de-energized and relay PCA would be down for making the second portion of the No. 3 control code (+), because this would result in picking up relay FA¹ at the field station.

From the above it will be observed that different code combinations in groups of two per step and a choice of four per step may be chosen for selecting different stations, by arranging the jumper connections 46 and 67 in different positions. It

will be obvious that sixteen combinations may be obtained with these two jumper arrangements for two steps and if an additional jumper is provided for the third step, sixty-four combinations are obtained. It will also be understood that more than one step may be provided for selecting additional control devices similar to levers SML and SGL and that the positions of two such devices may be repeated for each additional step provided.

It is believed that the typical arrangement shown and described is sufficient to illustrate the complete functioning of the system with respect to the provision of code combinations. It will be seen that the impulses applied to the line circuit during a control cycle always begin with a (+) and a combination of (+) and (-) impulses in line S follow, with line A either energized or de-energized in combination with line B for the return circuit.

These following impulses and the condition of conductor A are dependent upon the code jumper connections and the control lever positions made effective by the particular code determining relay CD which is picked up during the control cycle. Also, the character or polarity of the impulses in line S is selected by polarity determining relays PC for a (+) and NC for a (-) and the condition of the A line is selectively determined by relay PCA being down for a (+) and up for a (-). This latter reference to relay PCA, of course, does not mean that these (+) and (-) symbols refer to the polarity in any of the line conductors but, as above mentioned, are conveniently used in referring to the condition of relay FA¹ at the field station. The polarity of the impulses, as well as the condition of the A line return conductor are determined during the "off" periods in readiness for the application of the preselected codes during the following "on" periods.

Line pulsing and operation of stepping relays.—It has been explained that line S is normally de-energized and is energized during the operating cycle with polar impulses. Irrespective of the particular polarities with which line S is energized, relay FP in the control office and relay FP¹ at the field station repeat the operations of relays F and F¹, to effect the synchronous operation of the stepping relays in the control office and at the field stations.

Relay IV in the control office is picked up during the first "off" period by means of a circuit extending from (+), front contact 14 of relay SA, back contact 48 of relay FP, conductor 142, back contact 49 of relay VP, back contact 50 of relay 2V and winding of relay IV, to (-). Relay IV closes a stick circuit for itself extending from (+), front contact 14 of relay SA, stick conductor 64, front contact 51 of relay IV and winding of relay IV, to (-).

When relay IV is picked up, a circuit is completed for picking up relay E extending from (+), back contact 19 of relay 3V, back contact 20 of relay 2V, front contact 21 of relay IV, back contact 34 of relay VP, conductor 143 and winding of relay E, to (-). Relay E opens its back contact 33 which allows relay EP to drop and again energize line S by way of its back contact 27.

This is the first "on" period. Relays F and FP are now picked up in sequence and relay FP closes a circuit for actuating relay VP extending from (+), front contact 32 of relay SAP, front contact 52 of relay FP, front contact 53 of relay MBP, front contact 54 of relay MAP, conductor 144, back contact 55 of relay 3V, back contact 56

of relay 2V, front contact 57 of relay 1V and winding of relay VP, to (-). Relay VP establishes a stick circuit for itself extending from (+), front contact 32 of relay SAP, conductor 145, front contact 58 of relay VP and over the remainder of the above described pick-up circuit, to the winding of relay VP. This stick circuit for relay VP is effective until relay 2V is picked up during the second "off" period, which opens back contact 56 included in the stick circuit.

For maintaining relay VP in its actuated condition after relay 2V is picked up during the second "off" period, an additional stick circuit is established extending from (+), front contact 32 of relay SAP, back contact 52 of relay FP or back contact 59 of relay MBP or back contact 60 of relay MAP, one or more of which back contacts are closed during the "off" period and thence through conductor 146 and front contact 61 of relay VP, to the winding of relay VP.

The picking up of relay VP opens the circuit of relay E at its back contact 34, so that relay E drops after a short time interval, measured off by its slow releasing characteristics and closes the circuit for picking up relay EP which has been previously described. This advances the system from the first "on" period into the second "off" period, since the actuation of relay EP opens its contact 27 and de-energizes the S line, as well as the A and B lines.

This is the second "off" period. Relays F and FP are dropped and a circuit is established for picking up relay 2V extending from (+), front contact 14 of relay SA, back contact 48 of relay FP, conductor 142, front contact 49 of relay VP, back contact 62 of relay 3V, front contact 63 of relay 1V and winding of relay 2V, to (-). Relay 2V closes a stick circuit for itself by way of its front contact 65 to (+), on stick conductor 64. A circuit is now closed for picking up relay E which extends from (+), back contact 19 of relay 3V, front contact 20 of relay 2V, front contact 34 of relay VP, conductor 143 and winding of relay E to (-). Relay E opens its back contact 33 allowing relay EP to drop and again energize line S at its back contact 27. This advances the system out of the second "off" period.

This is the second "on" period. Relays F and FP are again picked up and relay VP is dropped, due to its pick-up and first stick circuit being open at back contact 56 of relay 2V and its second stick circuit being open at back contacts 52 of relay FP, 59 of relay MBP and 60 of relay MAP, all of these latter relays now being picked up. The circuit of relay E is now interrupted at front contact 34 of relay VP, allowing relay E to drop and establish the above described pick-up circuit for relay EP. Relay EP opens its back contact 27 which de-energizes the line conductors for advancing the system out of the second "on" period.

This is the third "off" period. Relays F and FP are again released and a circuit is established for picking up relay 3V extending from (+), front contact 14 of relay SA, back contact 48 of relay FP, conductor 142, back contact 49 of relay VP, front contact 50 of relay 2V and winding of relay 3V, to (-). Relay 3V establishes its stick circuit by way of its front contact 66 to (+) on stick conductor 64. A circuit is now established for picking up relay E extending from (+), front contact 19 of relay 3V, back contact 34 of relay VP, conductor 143 and winding of relay E, to (-). Relay E opens its back contact 33 which

drops relay EP and this in turn energizes line S by closing back contact 27, which is effective to advance the system out of the third "off" period.

This is the third "on" period. Relays F and FP are again picked up and a circuit is established for picking up relay VP which extends from (+), front contact 32 of relay SAP, front contact 52 of relay FP, front contact 53 of relay MBP, front contact 54 of relay MAP, conductor 144, front contact 55 of relay 3V and winding of relay VP, to (-). Relay VP again closes the above described stick circuit for itself, which extends through its front contact 58 and now includes front contact 55 of relay 3V. This sticks relay VP until the system advances through the "change to normal" period, when relays SA and SAP are dropped for interrupting all energized circuits to the winding of relay VP.

The circuit of relay E is now open at back contact 34 of relay VP and since relay 3V is picked up, the circuit through front contact 34 to relay E is interrupted. Relay E drops after a short time interval, causing relay EP to pick up and open line S at contact 27, which de-energizes the line conductors and advances the system out of the third "on" period.

This is the "change to normal" period. Relays F and FP are dropped and it will be assumed that relay 3V is the last stepping relay of the series. Relay LV has been shown in this embodiment to indicate how additional stepping relays are connected in the circuit when required. Relay LV is also shown with back contacts 24 and 127 which are for a purpose which will be later described. It will be understood that the last stepping relay of the series is connected in a manner indicated by the connections of relay LV. If there are only three steps actually used in the system, then of course, relay LV would be omitted and contacts 24 and 127 would be placed on relay 3V.

Relay E cannot be picked up during this last "off" period because its pick-up circuits are open at points on relays 3V and VP above described. Relay EP can not be dropped at this time because relay E does not open its circuit at back contact 33. This results in relays F and FP remaining down for a sufficient time to allow relay SA to drop, which opens its front contact 14 and allows all the stepping relays to be restored to normal, since (+) is removed from stick conductor 64. Relay SA opens its front contact 31 which de-energizes relay SAP, allowing this latter relay to release and by opening its front contact 32 causes the release of relay VP. Relay SAP, in opening its front contact 32, also opens the circuit of relay EP which allows this relay to drop away.

When the last stepping relay of the series is picked up (assuming this to be relay LV), the stick circuit of relay C is interrupted at back contact 24 of relay LV and relay C is released. The release of relay SA interrupts the stick circuit of relay STR at its front contact 16, which allows relay STR to be restored to normal. After the release of relay STR, the S line conductor is de-energized and the A and B line conductors are energized with (+) potential on the A line and (-) potential on the B line, as indicated in the second part of the "change to normal" period. Relays MA, MB and their repeating relays MAP and MBP now pick up and the system is advanced into the normal period with line S de-energized, the A line conductor energized (+) and the B line conductor energized (-).

It has already been mentioned that the stepping relays and the steering relays at the field stations operate in a manner similar to corresponding relays in the control office and for this reason it is not believed necessary to describe all the operating and pick-up circuits of these relays in detail. Relays 1V¹, 2V¹ and 3V¹ of Fig. 3 are picked up in synchronism with relays 1V, 2V and 3V of Fig. 2A.

10 The pick-up circuits of the stepping relays shown in Fig. 3 extend from (+), front contact 166 of relay SA¹, back contact 167 of relay FP¹ (which operates in synchronism with relay FP in the control office), and front contact 168 of relay SO¹, during the transmission of control impulses. The extension of this circuit to the stepping relay windings is through back and front contacts 169 of relay VP¹, which circuit is identical with that of Fig. 2A.

20 From the above description and by referring to the operation chart it will be observed that the stepping relays are picked up in rotation during successive "off" periods and the steering relays are shifted during the "on" periods. The 25 steering relays VP and VP¹ (and relays similar to VP¹ at other stations) pick up during the odd "on" periods and release during the even "on" periods.

30 Contacts 59 and 60 of relays MBP and MAP of Fig. 2B connected in multiple with back contact 52 of relay FP, are for the purpose of preventing the release of relay VP during the even "on" periods, until relays MBP and MAP are picked up. The purpose of contacts 53 and 54 of relays MBP and MAP in series with front contact 52 of relay FP, is to insure that relays MBP and MAP are picked up at the beginning of the odd "on" periods before relay VP can be picked up. These 35 four contacts on relays MBP and MAP therefore serve the purpose of holding back the shifting of relay VP until the relays, which are to be conditioned over the line conductors, are properly positioned.

40 During the "change to normal" period, the 45 stepping relays and the steering relays of Fig. 3 are released in a manner similar to those in the control office, when relay SA¹ drops and opens its front contacts 166 and 173.

45 Relay VPC¹ of Fig. 3 performs a function similar to that described in connection with contacts 50 53, 54, 59, and 60 of relays MAP and MBP in the control office. That is, this relay prevents the shifting of relay VP¹ until the relays in the line conductors have been properly conditioned. The 55 stick circuit of relay VP¹, extending through its front contact 172 is not interrupted during an even "on" period until relay VPC¹ picks up and opens its back contact 174. Relay VPC¹ can not pick up until both the A and B line impulsing 60 relays PLA¹ and PLB¹ are down. Therefore, relay VP¹ cannot drop until both the A and B line conductors are conditioned by relays PLA¹ and PLB¹ during the even "on" periods.

65 Furthermore, relay VP¹ cannot be picked up during the odd "on" periods until relay VPC¹ picks up and closes its front contact 179 and relay VPC¹, as above mentioned, cannot pick up until the A and B line conductors are conditioned by relays PLA¹ and PLB¹ being down. This insures that the relays at the field station in the A and B line conductors will be in their proper positions, as well as the relay in the S line conductor before relay VP¹ can be shifted.

70 It will be seen that during a control cycle, the 75 end of the normal period is marked off by relay

STR picking up and energizing the line. The start of the conditioning period is marked off by relay STR picking up and the end of the conditioning period is marked off by the picking up of relay EP. Similarly, the end of each "on" period and the start of each "off" period is marked off by the actuation of relay EP. The end of each "off" period and the beginning of each "on" period is marked off by the release of relay EP. The beginning of the "change to normal" "off" period 10 is marked off by the picking up of relay EP and the end of this period is marked off by the energization of the A and B lines exclusive of the stepping line, which is effective to pick up relays MA, MB, MAP and MBP. 15

During the transmission of indications, the normal period, the "off" periods, the "on" periods and the "change to normal" period are marked off in the same manner as during transmission of controls and during an indication cycle, 20 additional periods are included between the normal period and the first "off" period, with the "off" and "on" periods subdivided in a manner which will be specifically explained.

Transmission of controls.—During a cycle of 25 operations for the transmission of controls, the three line conductors are deenergized during the "off" periods. Line S is energized in accordance with the character of the code impulses, with lines 30 A and B serving as the return conductors during the "on" periods. It will be recalled that in some cases, lines A and B in multiple form the return circuit and in other cases line A is opened so that line B alone supplies the return path for the impulses applied to line S. It will now be assumed that the stepping relays in the control office and at the field station, together with the associated steering relays, operate as above described and an explanation will be given of the circuits which will be effective during this operation to transmit controls.

It will be recalled that line S is conditioned with a preliminary (+) impulse for picking up relays similar to SO¹ at the field stations and during this conditioning period, relays SA and SAP in 45 the control office and relay SA¹ at the field station are actuated. Relays similar to SA¹ at other field stations are likewise picked up.

It is assumed that the impulse applied to line S during the first "on" period is (+) for actuating relay F¹ of Fig. 3 to the right and that the A line conductor 11 is energized for picking up relay FA¹. The manner in which this combination is determined in the control office has been explained. During the first "on" period, the (+) 55 impulse applied to line S and the energized condition of line A (+) are executed at the field stations. The picked up position of relay FA¹ (in cooperation with relay F¹ positioned to the right) maintains the station relays similar to SO¹ 60 operated, which have code jumpers associated with the first step connected to control bus similar to 164.

It has been assumed that the station shown in Fig. 3 is the one to be selected and that all others 65 are dropped out. At those stations having a jumper similar to 175 connected to bus similar to 164, relays similar to SO¹ will be maintained energized during the first "on" period, by means of a circuit similar to that extending from (+), 70 front contact 177 of relay SO¹, back contact 161 of relay 3V¹, back contact 162 of relay 2V¹, front contact 163 of relay 1V¹, jumper 175 in its full line position, bus 164, front contact 165 of relay FA¹, contact 160 of relay F¹ in its right hand po- 75

sition and winding of relay SO^1 , to (-). At those stations not having a jumper similar to 175 connected to the bus similar to 164, the relays similar to SO^1 are dropped because the above circuit is incomplete.

When the system advances into the second "off" period, those relays similar to SO^1 which are up will be stuck up over a circuit similar to that extending from (+), front contact 177 of relay SO^1 , front contact 158 of relay SA^1 , back contact 159 of relay FP^1 , or make-before-break contact 160 of relay F^1 in its de-energized position, in multiple with contact 159, and winding of relay SO^1 , to (-). It is, of course obvious that the stick circuits of those relays similar to SO^1 which are dropped during the first "on" period are not complete during the second "off" period, since the above traced stick circuit is open at contacts similar to 177.

The system now advances into the second "on" period by means of a (-) impulse in line S. Relay $2V^1$ is up and relay V^1 is down during this period and a circuit is completed for holding relay SO^1 in its operated position, which extends from (+), front contact 177 of relay SO^1 , back contact 161 of relay $3V^1$, front contact 162 of relay $2V^1$, code jumper 180 in its full line position, bus 181, back contact 182 of relay FA^1 , contact 160 of relay F^1 in its left hand position and winding of relay SO^1 , to (-). Relay FA^1 is down at this time for closing its back contact 182 because the condition of line A is open (-), as above pointed out and relay F^1 is positioned to the left because of the (-) impulse applied to line S.

It will be understood that in the embodiment disclosed herewith, only the relay SO^1 of Fig. 3 will be maintained energized during this period, since it is assumed that complete station selection is accomplished with two steps. With two stepping relays used for station selection, four stations may be selectively chosen by dropping out one-half (2) of the stations on the first step which leaves two relays similar to SO^1 picked up. Then on the second step, one-half (1) of the remaining relays similar to SO^1 will be dropped, leaving only one (which is assumed to be relay SO^1 of Fig. 3) in its actuated position.

During the third "off" period, relay $3V^1$ is picked up and relay SO^1 is stuck up over the previously described circuit including its front contact 177 and make-before-break contact 160 of relay F^1 in its deenergized position, in multiple with back contact 159 of relay FP^1 . As soon as relay $3V^1$ picks up, (+) potential is connected through front contact 177 of relay SO^1 and front contact 161 of relay $3V^1$ to the winding of relay SO^1 , so that this relay is maintained energized during the remainder of this cycle. With relay SO^1 stuck up after station selection, additional impulses are effective to operate only those stepping relays at the station illustrated in Fig. 3 since the circuit for these relays is by way of front contact 168 of relay SO^1 only at the station illustrated.

During the third "on" period, which takes place after station selection, the No. 3 control (+)(-) is executed by actuating relay F^1 of Fig. 3 to the right and by deenergizing the A line conductor, which prevents the picking up of relay FA^1 . A circuit is now closed for actuating switch machine relay SMR^1 to the right which extends from (+), front contact 177 of relay SO^1 , front contact 161 of relay $3V^1$, contact 160 of relay F^1 in its right hand position, back contact 188 of relay LV^1 , front contact 183 of relay $3V^1$ and upper

winding of relay SMR^1 , to (-). With relay SMR^1 positioned to the right, a circuit is closed from (+), contact 184 of relay SMR^1 in its right hand position and normal operating winding of switch machine SM^1 , to (CN). This results in 5 operating the switch machine in such a direction that switch TS^1 is advanced to its normal locked position.

It will be understood that in the event of a (-) impulse applied to line S during the third 10 "on" period, relay F^1 would be positioned to the left and the above described circuit would be by way of contact 160 of relay F^1 actuated to the left, back contact 217 of relay LV^1 , front contact 218 of relay $3V^1$ and lower winding of relay 15 SMR^1 , to (-). This would result in positioning relay SMR^1 to the left and in closing its contact 20 184 at the left, the switch machine motor would be energized in the opposite manner for moving the track switch TS^1 to the reverse locked position.

During the third "on" period, the second portion of the No. 3 control is executed by closing a circuit which extends from (+), front contact 221 of relay SO^1 , front contact 224 of relay FP^1 , 25 contact 230 of relay F^1 in either position (this circuit being completed irrespective of the polarity in line S), back contact 229 of relay FA^1 , back contact 232 of relay LV^1 , front contact 233 of relay $3V^1$, and lower winding of relay SR^1 , to 30 (-). This is effective to position relay SR^1 to the left.

In the event that the second part of the No. 3 control is (+), determined by relay PCA in Fig. 35 2B being down so that the A line conductor is energized for picking up relay FA^1 , then relay SR^1 would be energized by way of its upper winding over a circuit which would extend from (+), front contact 221 of relay SO^1 , front contact 224 of relay FP^1 , contact 230 of relay F^1 , front 40 contact 229 of relay FA^1 , back contact 234 of relay LV^1 , front contact 235 of relay $3V^1$, and upper winding of relay SR^1 , to (-).

In brief, the positioning of levers SML and SGL of Fig. 2A determines the polarity applied 45 to the switch machine and signal relays SMR^1 and SR^1 and these relays in turn govern the operation of the switch machine and signal devices. Obviously, if the control lever SML is moved to a position out of correspondence with the track 50 switch TS^1 , this track switch will be operated but if the control lever is placed in a position which corresponds with the position of the track switch, then the track switch stays in its former position.

Under the heading "Polarity selection of impulses" it was explained how the four distinctive code combinations for each step are obtained. It has been pointed out above how the first one of these combinations (+)(+) is effective, by way of jumper 175 connected to bus 164, to maintain relay SO^1 in its actuated position during the first "on" period. The second one of these combinations (+)(-) requires jumper 175 to be in connection with bus 237 to hold relay SO^1 , 65 since relay F^1 would be actuated to the right and relay FA^1 would be down for this combination. The circuit of relay SO^1 would then be through back contact 165 of relay FA^1 and contact 160 of relay F^1 in its right hand position.

For the third combination (-)(+), jumper 175 would have to be connected to bus 238 to hold relay SO^1 , since relay F^1 would be actuated to the left and relay FA^1 would be up. The circuit of relay SO^1 would then be through front 75

contact 182 of relay FA¹ and contact 160 of relay F¹ in its left hand position. For the fourth combination (—)(—) jumper 175 must be connected to bus 181 to hold relay SO¹, since relay F¹ would be actuated to the left and relay FA¹ would be down. The circuit of relay SO¹ would then be through back contact 182 of relay FA¹ and contact 160 of relay F¹ in its left hand position.

It will thus be obvious how relays similar to SO¹ are selectively controlled on a choice of four combinations per step basis, by maintaining only those relays picked up at the stations where the code jumper 175 matches the polarity of energization of the line S, as well as the energized or deenergized condition of line A. A similar selection is made by means of code jumper 180 on the second step.

After station selection, the selective stick circuit of relay SO¹ is switched from jumpers 175 and 180 to front contact 161 of relay 3V¹, which holds relay SO¹ until the end of the cycle at which time relay 3V¹ releases. The (+) potential on front contact 161 of relay 3V¹ is extended to the selective contact 160 of relay F¹, so that selection is by way of the two channel circuits including front contacts 183 and 218 of relay 3V¹, during the third step and front contacts 188 and 217 of relay LV¹ when more than three steps are provided. These two channel circuits constitute a means controlled by relay F¹ for selectively positioning one two-position relay such as SMR¹ at each step. Two additional channel circuits controlled by relay FA¹ have (+) potential applied to them through contacts 229 of this relay and include contacts 232, 233, 234 and 235 of relays 3V¹ and LV¹ and lead to relays such as relay SR¹, so that these relays may each be actuated to either one of two positions during each step.

40 Although the detailed circuits of the signal relays or other control devices have not been shown, it will be understood that they function to complete circuits for operating the signal devices. Also, the step-by-step operation of the stepping relays may occur in sequence and in synchronism for as many steps as required to transmit controls to such other signal relays or devices as desired.

45 The transmission of controls as above explained in detail may be briefly understood by considering that the code sending relays PC, NC and PCA are preconditioned during each "off" period, for determining the character of the code impulse to be applied to the line conductors during the succeeding "on" period. The character of such succeeding impulse is recorded by means of the polar magnetic stick type relay F¹ and the neutral type relay FA¹. The recorded impulse is executed at the field station during the succeeding "on" period by conditioning relays similar to SO¹ during station selection and by positioning particular function control relays such as relays SMR¹ and SR¹ at the selected station after station selection.

50 This transmission of controls continues until the predetermined number of steps have been taken which, by way of example, has been specifically illustrated as including three steps, two of which have been employed for station selection followed by a single step which is employed for the transmission of the particular controls after station selection.

55 *End of control cycle.*—It has been explained that relays F, FP, SA and SAP and all stepping relays in the control office are released during the "change to normal" period which follows the

third "on" period. It will be recalled that the "change to normal" period is long compared with other "off" periods resulting in relays F and FP in the control office and relays F¹ and FP¹ at the field station being down for a time interval sufficient to allow relays SA, SAP and SA¹ to be released. The stepping relays and the associated steering or half step relay at the field station release when relay SA¹ drops and opens its contacts 166 and 173. The stick circuit of relay SO¹ including its front contact 171, is interrupted when relay 3V drops and opens its front contact 161 and since relays F¹, FP¹ and SA¹ are down at this time, there is no circuit for holding relay SO¹ and it is dropped.

60 It will be understood that relays similar to F¹, FP¹, SA¹ and the stepping and steering relays at other stations will also be released when line S is deenergized for a period of time sufficiently long to allow the other slow acting relays to be dropped.

65 Simultaneously with the dropping away of the stepping relays in the control office, the particular code determining relay CD, which was picked up during the cycle, is released so that the next code determining relay in order may be effective at the beginning of the next cycle, if its corresponding starting button has been actuated and this condition stored by a storing relay.

70 *Automatic start by a field station.*—With the system in a normal period or period of blank, it may be initiated into a cycle of operations from a field station, either in response to some automatic change in traffic conditions or in response to the operation of a traffic controlling device, resulting from the transmission of controls from the control office during a control cycle, when such a device assumes a new position.

75 For example, track switch TS¹ may be shifted from a normal to a reverse position in response to a control transmitted by lever SML, in a manner previously described. When the track switch responds to such a control it causes a relay (not shown) to momentarily interrupt the stick circuit of a change relay CHP¹ of Fig. 3. Similarly, track relay T¹ may be released by a change in traffic conditions caused by a train passing over the associated detector track circuit, in accordance with the usual practice. The release of relay T¹ likewise interrupts the stick circuit of relay CHP¹ in a manner which is well known. In brief, the stick circuit for relay CHP¹ is carried through front and back contacts of relay T¹. This stick circuit may similarly be carried through like contacts of other controlling devices at the field station.

80 Irrespective of the particular change which occurs, it results in dropping the change repeating relay CHP¹ which closes a pick-up circuit for relay PLA¹ extending from (+), back contact 236 of relay FP¹, back contact 156 of relay SA¹, back contact 157 of relay CHP¹ and lower winding of relay PLA¹, to (—). Relay PLA¹ closes a stick circuit for itself extending from (+), back contact 193 of relay SA¹, front contact 189 of relay PLA¹ and lower winding of relay PLA¹, to (—). The actuation of relay PLA¹ opens its back contact 190 which allows relay VPC¹ to release. Relay PLA¹ also opens the A line conductor 11 at its back contact 150 which results in dropping relays MA, MB, MAP and MBP in the control office.

85 Referring to the indication cycle portion of Fig. 4, the system is now in the first part of the initiating period with all three line conductors deenergized as indicated by reference character 75

O (open) associated with all three lines. The release of relay MAP closes a circuit for picking up relay FC extending from (+), back contact 69 of relay SAP, back contact 72 of relay STR, 5 back contact 70 of relay MAP and winding of relay FC, to (-). Relay FC prevents the picking up of relay C during this cycle by opening its circuit at back contact 23 of relay FC.

Relay FC closes a circuit for picking up relay 10 STR which extends from (+) back contact 32 of relay SAP, front contact 73 of relay FC and winding of relay STR, to (-). Relay FC also closes a stick circuit for itself extending from (+), back contact 127 of relay LV, conductor 147, front contact 15 contact 79 of relay FC and winding of relay FC, to (-). Relay FC also closes a circuit for picking up relay NC extending from (+), front contact 75 of relay FC, back contact 74 of relay C and lower winding of relay NC, to (-). 20 Since this is a cycle for the transmission of indications, all of the impulses applied to line S are (-) because relay NC is held in its picked up position throughout the cycle over the above described circuit. The operation of relays NC and 25 STR close a circuit for energizing line S with (-) potential, which extends from the (-) terminal of battery B, back contact 8 of relay PC, front contact 26 of relay NC, winding of relay F and back contact 27 of relay EP to line S. The return 30 path extends through the line relays at the field stations, resistance coils R¹ and R² at the last field station, back contacts of relays such as PLB² at other field stations, conductor 152, back contact 153 of relay PLB¹, B line conductor 12, 35 winding of relay MB, conductor 124, front contact 7 of relay NC, back contact 25 of relay PC and front contact 10 of relay STR, to the (+) terminal of battery B.

The circuit branches at resistance coil R¹ and 40 leads through relays such as relay FA² at other stations, back contacts such as PLA² at other stations, conductor 151, winding of relay FA¹, front contact 150 of relay PLA¹, lower winding of lock-out relay LO¹, back contact 191 of relay SA¹, 45 B line conductor 12, winding of relay MB, conductor 124, front contact 7 of relay NC, back contact 25 of relay PC and front contact 10 of relay STR, to the (+) terminal of battery B.

It will be noted from the above traced circuit 50 that the A line conductor 11 is open toward the control office, at back contact 150 of relay PLA¹ at the station initiating the call. The A line conductor 151, extending toward stations farther away from the control office, is connected to the 55 B line conductor at the station initiating the call, through the lower winding of relay LO¹. The resistance coils R¹ and R² provide a sufficient drop in the A and B line conductors extending from the station shown in Fig. 3 to the end of the 60 line, so that the lower winding of relay LO¹ is not sufficiently shunted to prevent its operating.

With the system in the second part of the initiating period, line S energized (-), line A extending to the control office deenergized and line B 65 energized (+), relays MB and MBP in the control office are picked up and relays F and F¹ are positioned to the left. Relays FP in the control office and FP¹ at the field station are picked up over circuits closed by contacts 29 and 154 of relays F and F¹ respectively in their left hand dotted 70 positions. Relay LO¹ is picked up by the current flowing in line conductor 151 over the circuit above described. Relay FA¹ also picks up but is ineffective at this time.

75 The system is now in the lock-out period. Re-

lay SA in the control office is picked up over its previously described pick-up circuit and a circuit is closed for sticking relay MBP extending from (+), front contact 14 of relay SA, stick conductor 64, back contact 71 of relay E, front contact 78 and upper winding of relay MBP, to (-).

Relay SA¹ at the field station is picked up over a circuit completed at front contact 155 of relay FP¹. With relays FP¹ or SA¹ up, no other relay similar to PLA¹ can be picked up, because the pick-up circuit is open at back contacts similar to 156 or 236. Relay SA¹ closes a stick circuit for relay LO¹ extending from (+), front contact 193 of relay SA¹, front contact 194 and upper winding of relay LO¹, to (-). The picking up of relay SA¹ 15 opens the pick-up circuit of relay PLA¹ at back contact 156 and the stick circuit of relay PLA¹ at back contact 193 so that relay PLA¹ is dropped.

The system is now advanced into the conditioning period. The A line conductor is energized 20 due to the current in conductor 151 through back contact 150 of relay PLA¹, A line conductor 11, winding of relay MA, conductor 76, back contact 15 of relay PCA, front contact 13 of relay STR, front contact 7 of relay NC, back contact 25 of relay PC and front contact 10 of relay STR, to the (+) terminal of battery B. As shown in the operation chart during the conditioning period, line S is energized (-) and lines A and B are energized 30 (+).

Relays MA and MAP in Fig. 2D pick up when the A line is energized during this period and relay MAP establishes a stick circuit for itself extending from (+), on stick conductor 64, back contact 71 of relay E, front contact 80 and upper winding of relay MAP, to (-). Relay SAP is picked up when relay SA closes its front contact 31. Relay VPC¹ of Fig. 3 is again picked up when relay PLA¹ releases, by the closure of its back contact 190. Relay EP of Fig. 2B is picked up during 40 the conditioning period over a circuit extending from (+), front contact 32 of relay SAP, back contact 33 of relay E and lower winding of relay EP, to (-). Relay EP opens the S line conductor at its back contact 21, which deenergizes the three 45 line conductors 28, 11 and 12 to advance the system out of the conditioning period.

This is the first "off" period. The stepping 50 relays and their associated steering relays in the control office and at the field stations are operated in synchronism during an indication cycle in the same manner as previously described in connection with a control cycle, so that the detailed description of this operation will not be repeated. The line conductor S is impaled by 55 relay EP in the same manner as previously described, so that the detailed description of this operation will not be repeated. The relays similar to SO¹ of Fig. 3 are not picked up during an indication cycle, because the conditioning impulse is (-) which actuates relays similar to F¹ to the left, so that the circuits for picking up relays similar to SO¹ are incomplete. Since relay LO¹ is picked up, a circuit is completed for the stepping relays by way of front contact 170 of 60 relay LO¹.

Stored office and field starts.—It has previously been mentioned that, in the event of several stored office and field start conditions, the communication system functions to send alternate 70 controls and indications on separate cycles of operation. Before proceeding with the detailed description of the circuit operations under this condition, a brief summary will be given of the functioning of the system when a plurality of 75

office start conditions are stored and when a plurality of field start conditions are stored. Assuming that there are no field start conditions stored and that several storing relays in the control office have controls stored for transmission, a relay similar to relay CD of Fig. 2A will be picked up, which relay occupies the position of preference in the bank of CD relays. Relays C, STR and PC will then be picked up, a preliminary (+) impulse will be applied to line S and a cycle of operations will follow for selecting the station associated with the operated CD relay and for transmitting controls to this station.

At the end of the operating cycle, the operated CD relay will be released and the next one in preferred order will be picked up for again operating relays C, STR and PC and this next cycle will likewise be for the transmission of controls.

In the event of a plurality of field stations having new indications to be transmitted at substantially the same time, it will be understood that two or more relays similar to CHP¹ of Fig. 3 at different stations may be down during the normal period, so that two or more relays similar to PLA¹ may be picked up. This results in dropping relay MAP in the control office and picking up relays FC, STR and NC to initially energize line S with a (—) polarity, for operating relay SEL to mark the cycle for the transmission of indications. Only one relay similar to relay LO¹ in Fig. 3 can be picked up at one time, so that only the station with its LO relay up is effective to register itself in the control office and transmit indications.

At the end of the cycle, the lock-out relay at the station transmitting indications is released when the relay similar to relay SA¹ drops and opens the stick circuit of the lock-out relay. During this cycle, relays similar to relay PLA¹ at stations other than the one which obtained access to the line are not held in their picked up positions, because their upper windings are open at contacts similar to 199 of relays similar to relay LO¹ and their lower windings are incomplete at back contacts similar to 156 of relays similar to relay SA¹.

At the end of the cycle when all of the relays similar to relay SA¹ are dropped, other relays similar to relay PLA¹ at the various stations having new indications to transmit may be picked up. The circuits will then function as described above so that only one lock-out relay can be picked up and this takes place at the waiting station nearest the end of the line. After the termination of this cycle of operations when indications are transmitted, then another lock-out relay may be picked up and this takes place in rotation until all stations with new indications to transmit have been satisfied.

Considering the case of a plurality of simultaneous office and field start conditions stored, it is obvious from the above description that only one CD relay can be picked up at the start of such a cycle and that relay MAP may be down at the start of this cycle. This results in picking up relay C by means of the circuit extending through back contact 16 of relay SA, conductor 136, front contact 17 of relay CD, conductor 137 and back contact 23 of relay FC, to the winding of relay C. Of course, if relay FC is up, the above described circuit for relay C is not complete and the cycle will function for the transmission of indications.

Assuming that relay C is picked up, it will be

stuck up until relay LV is picked up and relay SEL is down. The circuit for picking up relay FC and sticking it up until both relays LV and SEL are simultaneously up has been described. Relay STR is picked up over a circuit which includes either front contact 18 of relay C or front contact 13 of relay FC and has been previously described. Relay PC is operated by means of the previously described circuit, which is effective to determine this the first cycle as a cycle for the transmission of controls, by conditioning line S with a (+) potential. Relays F, FP, SA and SAP now function as above described. Relay SEL does not pick up during this cycle.

Relay C is dropped when relay LV picks up at the last step and opens its back contact 24, since relay SEL is down with its front contact 130 open. The release of relay C closes a circuit for picking up relay NC which extends from (+), front contact 75 of relay FC, back contact 14 of relay C and lower winding of relay NC, to (—).

At the end of the first cycle, relay STR is momentarily dropped when relay SA drops and opens its front contact 16, but relay STR again picks up as soon as relay SAP drops and closes its back contact 32. Another CD relay will be picked up and relay FC will not be dropped at the end of the first cycle, being stuck up over a circuit extending from (+), through back contact 130 of relay SEL and front contact 79 of relay FC to its winding. Relay NC remains up and marks the second cycle as one for the transmission of indications.

Relay FC remains up during the second (indication) cycle until relay LV picks up, which opens its back contact 127 and since relay SEL is up at this time, the stick circuit of relay FC is interrupted and it is released. Relay SA now releases and relay STR momentarily releases as before, but is picked up when relay SAP releases. Relay STR is adjusted to be slightly slow in picking up so that relay FC will have time to operate before relay STR gets up and opens the pick-up circuit of relay FC at its back contact 72. The dropping of relay SAP simultaneously closes the pick-up circuits of relays FC and STR so that it is necessary that relay STR be adjusted in a manner to make it slow to pick up.

At the time relay STR releases at the end of the second (indication) cycle, relay PC is picked up over the circuit including front contact 22 of relay C. Relay C is stuck up until the end of the third cycle and relay SEL is dropped at the start of the third cycle when relay SAP drops and opens its stick circuit, including its front contact 131 and front contact 69 of relay SAP.

It will be noted that relays C and FC are both again picked up, which is effective to determine the third cycle as a control cycle. At the end of the third cycle relay C will be released when relay LV picks up, closing a circuit for picking up relay NC, which will mark the fourth cycle as a cycle for the transmission of indications. This fourth cycle will be an indication cycle because relay C is down, relay FC is stuck up and relay SEL is picked up. The pick-up circuit of relay SEL is effective at the start of each indication cycle and extends from (+), back contact 31 of relay SA, contact 39 of relay F and winding of relay SEL, to (—).

In brief, relay SEL responds to the polarity of the conditioning impulse applied to line S, so as to be up for an indication cycle and down for a control cycle. The control office start relay C and the field start relay FC are both stuck up

when picked up, by way of circuits extending through back contacts of the last stepping relay LV in combination with front and back contacts on relay SEL. This combination of contacts 24, 5 127 and 136 on relays LV and SEL, cause relay C to drop at the end of a control cycle (relay SEL down) while relay FC will be held up. At the end of an indication cycle, relay FC will drop and relay C will pick up. At the start of the succeeding control cycle relay FC will be again picked 10 up so that both of these start relays are up during a control cycle.

When the system goes into the normal period with both relays C and FC down, relay C may 15 pick up first through back contact 16 of relay SA and then relay FC may pick up through back contact 69 of relay SAP so that if there is a start stored in both the field and the control office, both relays C and FC pick up. The control office 20 start has preference (relay C up) and the first cycle will be a control cycle, at the end of which relay C will drop but relay FC will remain up. The next cycle will then be an indication cycle at the end of which relay FC drops and then relay 25 C may pick up and relay FC may again pick up.

Registration of a field station.—In the present embodiment in which two stepping relays are provided for station selection, it has been explained how a choice of four code combinations 30 per step has been obtained for the transmission of controls, these combinations being determined by the polarity with which line S is impulsed and the energized or deenergized condition of line A for the return. In connection with the transmission 35 of indications, the A and B line conductors are so conditioned that a choice of two indications is obtained during one part of each "on" period and a choice of three indications is obtained during another part of each "on" period, thus resulting in a selection of five combinations 40 for step.

For convenience in describing the manner in which a choice of five combinations per step is obtained during an indication cycle, the indications obtained during the first part of the "on" 45 period (selected and stored during the next preceding "off" period) are referred to as "off" indications. The "on" indications are selected, stored and conditioned during the "on" period and these, together with the "off" indications are executed 50 during a portion of the "on" period and a portion of the next succeeding "off" period, as indicated in Fig. 4.

It is believed that this feature of the invention 55 may be best understood by assuming that the field station shown in Fig. 3 is assigned code combination $(-)(-)(+)$, as indicated in the station registration period at the lower part of the indication cycle of Fig. 4. The above assumption 60 means that the No. 1 "off" indication is executed $(-)$ because relay MX is down, connecting $(B-)$ to the No. 1 "off" indication bus 89 of Fig. 2C. The No. 1 "on" indications are executed $(-)$ and $(+)$ because relay MAP is down, connecting $(B-)$ to the No. 1A "on" indication bus 105 and because relay MBP is up connecting $(B+)$ to the No. 1B "on" indication bus 109.

It will be noted that this station registering 70 code is obtained with only one step of the step-ping relay bank. The choice during the "off" period is $(+)$ or $(-)$ and the choice during the "on" period is first $(-)(+)$, second $(+)(-)$, third $(+)(+)$, a total of five choices. This does not mean that the line circuits are energized 75 $(+)$ and $(-)$ but is simply a convenient manner

of explaining the different combinations obtained. The $(+)$ or $(-)$ "off" refers to relay MX up and down respectively. The "on" choices refer to; first relays MAP down and MBP up; second relays MAP up and MBP down; third relays MAP 5 up and MBP up, all as determined by the combinations of the A and B lines for the return circuit for line S.

It has been explained how the system is advanced into the first "off" period during an indication cycle. The stepping line S and the return lines A and B are all deenergized during the first "off" period, resulting in picking up relays IV and IV¹. Relays F and FP are dropped during the first "off" period and relays MAP and 10 MBP are stuck up by means of a circuit extending form $(+)$, front contact 14 of relay SA, stick conductor 64, back contact 77 of relay E and front contacts 88 and 78 of relays MAP and MBP 15 respectively, to the upper windings of these relays. 20

Relay E is picked up during the second part of the first "off" period, which opens the above described stick circuit of relays MAP and MBP 25 and these two relays are released. Relay MX is not picked up during this period, because the pick-up circuit through its lower winding is open at back contact 100 of relay MBP when this relay is up and at front contact 81 of relay MAP when 30 this relay is down.

When relay IV¹ of Fig. 3 picks up during the first "off" period, a circuit is completed for picking up relay PLA¹ which extends from $(+)$, back contact 236 of relay FP¹, front contact 156 of 35 relay SA¹, "off" indication bus 191, code jumper 196 in its full line position, No. 1A "off" indication bus 209, front contact 206 of relay IV¹, back contact 207 of relay 2V¹, back contact 208 of relay 3V¹, back contact 233 of relay LV¹, back contact 209 of relay VP¹, upper winding of relay 40 PLA¹, front contact 199 of relay LO¹ and back contact 240 of relay SO¹, to $(-)$. Relay PLA¹ is down during this "off" period because the No. 1B "off" indication bus 201 is not energized.

The system is next advanced into the first 45 "on" period by the dropping of relay EP in the control office and the energization of line S. The return circuit is by way of line B alone because relay PLA¹ is up which opens line A at its back contact 150. With the return circuit extending over line B, relays F, FP, MB and MBP are picked up in the control office. With relay MAP down and relay MBP up, there is no circuit for picking up relay MX so that the No. 1 "off" indication is conditioned $(-)$ by relay MX connecting 50 $(B-)$ to conductor 94 to be executed later.

With relay PLA¹ up, the circuit of relay VPC¹ 55 is open at back contact 190 so that relay VPC¹ is dropped. During the first part of the first "on" period, relays F¹ and FP¹ at the field station are picked up, which results in disconnecting $(+)$ potential from "off" indication bus 197 at back contact 236 of relay FP¹. Relay PLA¹ is therefore, released which results in energizing 60 the A line and picking up relays MA and MAP in 65 the control office. Relay MX can not be operated under this condition because both relays MAP and MBP are up which leaves the energizing circuit for the lower winding of relay MX incomplete. 70

When relay PLA¹ drops at the field station, the circuit of relay VPC¹ is again completed and this relay picks up. Relays FP, MAP and MBP in the control office are up and the circuit is com- 75

pleted for picking up relay VP which has been previously described. With relay VPC¹ at the field station up, the circuit is completed for picking up relay VP¹, which extends from (+), front contact 173 of relay SA¹, front contact 186 of relay FP¹, front contact 179 of relay VPC¹, back contact 187 of relay 3V¹, back contact 222 of relay 2V¹, front contact 223 of relay IV¹ and winding of relay VP¹, to (-).

10. It will thus be evident that the combination indicated in the operation chart for the second part of the first "on" period, that is, line S (-) and lines A and B (+) controls the picking up of relay VP in the control office and relay VP¹ at the field stations in synchronism. This feature is provided as a means for synchronizing the steering and stepping relay operations at the control office and at the field station.

With the VP and VP¹ relays up, the system is advanced into the third part of the first "on" period by picking up relay PLA¹ over a circuit extending from (+), code jumper 198, in its full line position, No. 1A "on" indication bus 204, front contact 210 of relay IV¹, back contact 211 of relay 2V¹, back contact 212 of relay 3V¹, back contact 241 of relay LV¹, front contact 209 of relay VP¹, upper winding of relay PLA¹, front contact 199 of relay LO¹ and back contact 243 of relay SO¹, to (-). Relay PLB¹ remains down at this time because the No. 1B "on" indication bus 205 is deenergized.

With relay PLA¹ up and relay PLB¹ down, the A line is deenergized and the return circuit for line S is by way of line B alone, which results in dropping relays MA and MAP and holding relays MB and MBP in their operated positions. As indicated in the third part of the first "on" period, this is the point in the cycle when the No. 1 "on" indication is conditioned. In the present example, with the B line energized and the A line deenergized, relay MAP is down which connects (B-) to conductor 32 and relay MBP is up which connects (B+) to conductor 83, for later executing the first "on" indication.

45. The picking up of relay VP during the second part of the first "on" period opens the circuit of relay E, in a manner which has already been explained and after a brief time interval relay E releases its armature and closes the executing circuits for the No. 1 indications, which have been conditioned as described.

It will be recalled that relay MX is down so that a circuit is now closed from (B-), back contact 103 of relay MX, conductor 84, back contact 85 of relay E, front contact 132 of relay SEL conductor 280, front contact 86 of relay VP, back contact 81 of relay 3V, front contact 88 of relay IV, No. 1 "off" indication bus 89 and winding of relay IPT to (CN). This results in actuating relay IPT to the left as shown.

Recalling that relay MAP is down, a circuit may now be traced for executing the No. 1A "on" indication, which extends from (B-), back contact 90 of relay MAP, conductor 82, back contact 91 of relay E, front contact 133 of relay SEL, conductor 281, front contact 92 of relay VP, back contact 93 of relay 3V, front contact 104 of relay IV, No. 1A "on" indication bus 105 and winding of relay 2PT to (CN). This results in actuating the contacts of relay 2PT to the left as shown.

It will likewise be recalled that relay MBP is up so that a circuit for executing the No. 1B "on" indication is completed from (B+), front contact 94 of relay MBP, conductor 83, back contact

95 of relay E, front contact 134 of relay SEL, conductor 282, front contact 96 of relay VP, back contact 97 of relay 3V, front contact 98 of relay IV, No. 1B "on" indication bus 109 and winding of relay 3PT, to (CN). The current in this circuit is in such a direction that relay 3PT is positioned to the right as shown.

The system is next advanced into the second "off" period and as indicated in the operation chart and as will be apparent from an examination of the circuits above traced, the No. 1 execution circuits remain effective during the first part of the second "off" period. These execution circuits are broken at contacts 85, 91 and 95 of relay E when this relay is picked up to mark the beginning of the second part of the second "off" period. Relay 2V is picked up in the first part of the second "off" period, which closes a circuit for operating relay ST of Fig. 2C extending from (+), front contact 120 of relay 2V, contact 121 of relay IPT in its left hand position, contact 122 of relay 2PT in its left hand position, contact 123 of relay 3PT in its right hand position and the winding of relay ST, to (-).

The above detailed description sets forth the manner in which the field station shown in Fig. 3, having an assumed code combination (-)(+)(+), registers itself in the control office by selecting and operating relay ST of Fig. 2C. The code combination of this station is determined by code jumpers 196 and 198 being connected as shown in the lower right hand portion of Fig. 3. The selection of one of two combinations during the "off" period is obtained by selectively connecting code jumper 196 to indication buses 200 and 201.

With jumper 196 connected as shown, relay MBP is up, relay MAP is down which leaves relay MX down to execute a (-) "off" code as specifically pointed out. The alternate connection of jumper 196 to indication bus 201 would result in picking up relay PLB¹, so that the return circuit would be established by way of line A, resulting in relay MAP being up and relay MBP being down, which would complete a circuit for picking up relay MX. With relay MX up, the "off" code combination executed would be (+). This is the choice of two code combinations for the "off" period.

With jumper 198 connected as shown in Fig. 3, relay PLA¹ is picked up, the A line conductor is opened and the return circuit is by way of the B line conductor alone, which results in relay MBP picking up and relay MAP remaining down. With relay MAP down, relay 2PT is positioned to the left and with relay MBP up, relay 3PT is positioned to the right as has been explained in detail.

In the event that code jumper 198 is connected to indication bus 205, relay PLB¹ would be up and relay PLA¹ down which would open the B line conductor, establishing the return circuit by way of the A line conductor alone. This would pick up relays MA and MAP and relays MB and MBP would remain down. With relay MAP up, the No. 1A "on" indication bus of Fig. 2C would be energized (+) for positioning relay 2PT to the right. With relay MBP down, the No. 1B "on" indication bus would be energized (-) for positioning relay 3PT to the left.

If jumper 198 of Fig. 3 is not connected to either bus 204 or 205, then both relays PLA¹ and PLB¹ remain down, establishing the return circuit by way of both the A and B line conductors, which would result in both relays MAP 75

and MBP picking up. A (+) potential would then be applied to both the No. 1A "on" and the No. 1B "on" indication buses for positioning relays 2PT and 3PT to the right. This is the 5 method of obtaining a choice of three combinations during the "on" period.

It will be understood that there is no combination for positioning relays 2PT and 3PT both to the left during an "on" period, because this 10 would require both the MA and MB relays being down. This is not possible during an "on" period since one, the other or both the A and B line conductors must be energized for the return circuit for line S.

15 Conductors 1 to 6 inclusive leading to bracket STN show where the six station relays are connected for selectively registering any one of six stations in the control office during a single step of an indication cycle.

20 *Transmission of indications.*—Relays 2V and 2V¹ are picked up during the first part of the second "off" period. The No. 2 "off" indication is conditioned after the picking up of these two stepping relays, during the second part of the 25 second "off" period and the first part of the second "on" period. With relays 2V¹ and VP¹ at the field station picked up, a circuit is closed for picking up relay PLB¹ which extends from (+), back contact 236 of relay FP¹, front contact 156 30 of relay SA¹, "off" indication bus 197, front contact 213 of relay T¹, No. 2B "off" indication bus 203, front contact 214 of relay 2V¹, back contact 215 of relay 3V¹, back contact 242 of relay LV¹, front contact 216 of relay VP¹, winding of relay 35 PLB¹, front contact 199 of relay LO¹ and back contact 240 of relay SO¹, to (—). Relay PLA¹ is not picked up during the second "off" period because the No. 2A "off" indication bus 202 is deenergized.

40 With relay E of Fig. 2B picked up following the picking up of relay 2V in a manner which has been previously described, relay MBP is dropped because relay E opens its stick circuit at back contact 77. Relay MAP is already down and the system therefore goes through the 45 second part of the second "off" period with relays MAP, MBP and MX down.

When relay EP drops and closes the line to advance the system into the first part of the second "on" period, line S is energized and the return circuit is by way of the A line because relay PLA¹ is down, which completes the A line circuit at its back contact 150. Relay PLB¹ is up which opens the B line at its back contact 153.

50 Relays F, FP, MA and MAP now pick up and with relay MAP up and relay MBP down, a circuit is closed for picking up relay MX which extends from (+), back contact 19 of relay 3V, front contact 20 of relay 2V, front contact 34 of relay VP, conductor 143, back contact 99 of relay EP, conductor 148, lower winding of relay MX, back contact 100 of relay MBP and front contact 81 of relay MAP, to (—). Relay MX 55 closes a stick circuit for itself extending from (+), front contact 135 of relay FP, front contact 102 and upper winding of relay MX, to (—). Relay MAP is up, relay MBP is down and relay MX is up at this time.

70 The system is now advanced into the second part of the second "on" period by the picking up of relay FP¹ at the field station. The circuit above traced for picking up relay PLB¹ is now interrupted at back contact 236 of relay FP¹ so 75 that relay PLB¹ releases. This energizes both

the A and B line conductors and as a result relays MB and MBP are picked up. With relay MAP up and relay MBP up, the pick-up circuit of relay MX is opened but relay MX remains stuck up to (+) potential at front contact 135 of 5 relay FP.

With relays MAP, MBP and FP all up, the stick circuit of relay VP is interrupted at back contacts 60, 59 and 52 of these respective relays. With relays PLA¹ and PLB¹ down, relay VPC¹ is again 10 picked up over the previously described circuit and it opens its back contact 174, which interrupts the stick circuit of relay VP¹ including front contact 172 of this latter relay.

15 Relay VP¹ drops and establishes the conditioning circuit for the second "on" indication. The second "on" indication circuits as well as the third "off" and third "on" indication circuits are not shown completed, since it is believed that the above examples relating to the first "off" and 20 "on" indications and the second "off" indications are sufficient to provide an example of the manner in which all such indications function.

25 Since relay MX of Fig. 2D is up, being so positioned by the No. 2 "off" indication, a circuit is effective during the fourth part of the second "on" period for executing this indication. The release of relay VP during the second part of the second "on" period opens the circuit of relay E, allowing this latter relay to drop and close the executing circuits for the No. 2 indications. Although the No. 2 "on" indications have not been shown in detail, the No. 2 "off" indication is shown as being executed over a circuit extending 30 from (B+), front contact 103 of relay MX, back contact 85 of relay E, front contact 132 of relay SEL, conductor 280, back contact 86 of relay VP, front contact 106 of relay 2V, No. 2 "off" bus 107, front contact 108 of relay ST and winding of 35 relay IR¹, to (CN). The current flow in this circuit is effective to position relay IR¹ to the right as shown. Relay IR¹ selectively conditions conductor 126 so as to condition lamp OS.

40 It will be apparent that relays MAP and MBP are conditioned by means of circuits controlled 45 by the No. 2 "on" indication buses 219 and 220 shown in the lower right hand portion of Fig. 3, in the same manner as explained in connection with the No. 1 "on" indication buses.

45 The system is next advanced into the third "off" period, with the No. 2 execution circuits remaining effective during the first part of this period. These execution circuits are broken at contacts 85, 91 and 95 of relay E when it picks up to mark the beginning of the second part of 50 the third "off" period.

55 Relays 3V and 3V¹ are picked up during the first part of the third "off" period and the No. 3 "off" indication is conditioned by means of circuit 60 connections which are not shown in detail, but which are indicated in the lower right hand portion of Fig. 3 and which will be obvious from the above examples.

65 When relay E of Fig. 2B picks up after the picking up of relay 3V, relay EP is dropped and the line circuit is closed at its back contact 27, for advancing the system into the first part of the third "on" period. Line S is energized and the return circuit is by way of the A and/or B line 70 conductors as conditioned by the field station. Relays F and FP now pick up and the system advances into the second part of the third "on" period. Relays FP, MAP and MBP will pick up in the manner previously described for closing the 75

pick-up circuit of relay VP extending from (+), front contact 32 of relay SAP, front contact 52 of relay FP, front contact 53 of relay MFP, front contact 54 of relay MAP, conductor 144, front contact 55 of relay 3V and winding of relay VP, to (-).

At the field station a circuit is effective for picking up relay VPC¹ when relay PLA¹ is dropped and with relay VPC¹ up, the previously described 10 circuit is completed for picking up relay VP¹, except that it now extends through front contact 187 of relay 3V¹ instead of contact 223 of relay 1V¹. With relay VP¹ up, the No. 3 "on" conditioning 15 circuits are established, which circuits are not shown complete. Relay E in the control office is released during the fourth part of the third "on" period to execute the No. 3 indications.

It is believed that the example specifically described is sufficient to indicate how a selection of 20 five indication choices is obtained during each step. These five choices have been described in detail and relate to the No. 1A "off", No. 1B "off", No. 1A "on", No. 1B "on", No. 2A "off" and No. 2B "off" buses shown in Fig. 3.

25 The above example shows how the indication storing relay IR¹ is selectively positioned to obtain a choice of two indications during the second step of the stepping relay bank. With two additional indication storing relays positioned by 30 means of the No. 2 "on" indication combinations, in a manner similar to the positioning of relays 2PT and 3PT by the No. 1 "on" indication combinations, it is evident how a choice of five indications is obtained during the second step.

35 It will be understood that additional pilot relays similar to 1PT, 2PT and 3PT may be provided and positioned during additional steps and it will be obvious that the provision of one additional group of these pilot relays will result in the selection 40 of thirty-six code combinations during two steps, by pyramiding the contacts of these relays in a manner illustrated in Fig. 2C.

In the event that two steps are used for station 45 selection, two additional code jumpers similar to 196 and 198 of Fig. 3 will be provided for selectively connecting to the No. 2 "off" indication buses 202 and 203 and the No. 2 "on" buses 219 and 220. In this event, the contacts of relay T¹ would be connected to the next group of indication 50 buses in the series.

55 *End of indication cycle.*—The stepping and impulsing operations during an indication cycle are similar to those effected during a control cycle. Line S is deenergized when relay EP of Fig. 2B picks up to mark the end of the third "on" period and the beginning of the "change to normal" period. The "change to normal" period is long compared with other "off" periods, which results in relays F and FP in the control office and relays 60 F¹ and FP¹ at the field station remaining down for a sufficiently long interval to permit relays SA, SAP, and SA¹ to restore to normal.

The stepping relays and the steering or half step relays are released in the manner described 65 in connection with a control cycle. Relay FC of Fig. 2B is restored to normal when relay LV is picked up and opens its back contact 127. Relay NC is released by the opening of front contact 75 when relay FC is dropped. Relay STR is released when relay SA drops and opens its front contact 16 to interrupt the stick circuit of relay STR.

75 Relay LO¹ of Fig. 3 is deenergized when relay SA¹ releases and opens its front contact 193 included in the stick circuit of relay LO¹. The A

and B line conductors are now energized and the system is advanced into the normal period, in the same manner previously described in connection with a control cycle. With the stepping relays of Fig. 2A in their normal positions, the executing 5 circuits including conductors 89, 105, 109, and 107 are all opened, so that the pilot relays and the indication storing relays are deenergized and left in the positions to which they were actuated. Relay ST is restored to normal when relay 2V 10 drops and opens its front contact 120.

Lock-out between field stations.—In the event that changes have taken place at several field stations simultaneously or in rapid succession, so that more than one field station has indications 15 to transmit at the beginning of a cycle, it is necessary to provide means for preventing more than one station obtaining access to the communication circuit at one time. In this embodiment, preference is given to the field station 20 nearest the end of the line.

It has been explained that the picking up of a relay similar to relay SA¹ of Fig. 3 during the lock-out period, prevents the operation of any relay similar to relay PLA¹ which is not up at 25 this time. When a single station starts the cycle of operations by picking up its relay similar to relay PLA¹, other stations are prevented from breaking in during this same cycle, when relay FP¹ picks up and opens its back contact 236. It 30 may occur, however, that two or more relays similar to relay CHP¹ may be down at the same time while the system is in its normal or its initiating period. In this case two or more relays similar to relay PLA¹ may be picked up over circuits similar to that previously described in connection with relay PLA¹ of Fig. 3.

It is believed that the lock-out feature may be best understood by assuming that two relays similar to relay PLA¹ are picked up at the same time and explaining how only the station nearest the end of the line effects control of the communication system under this condition. It will be understood that the operation is the same when more than two relays similar to relay PLA¹ are 45 up at the same time, since only the station nearest the end of the line in this instance will be able to transmit indications. At the start of the next cycle, the station next in order nearest the end of the line will obtain access to the communication system and so on.

50 It will be assumed that relay PLA¹ of Fig. 3 is at the station nearest the end of the line. The two relays similar to relay PLA¹ which are assumed picked up are stuck up over a circuit similar to that extending from (+), back contact 193 of relay SA¹, front contact 189 of relay PLA¹ and lower winding of relay PLA¹, to (-). When relays STR and NC of Fig. 2B pick up during the initiating period, current flowing over line S 55 through resistance coil R¹ at the last station, relay FA² and back contact PLA², extends by way of conductor 151, winding of relay FA¹, front contact 150 of relay PLA¹, lower winding of relay LO¹, back contact 191 of relay SA¹ and thence 60 by way of the B line conductor to the other side of battery B in the control office.

65 This circuit through the lower winding of relay LO¹ exists only at the station nearest the end of the line, since at the other station nearer the 70 control office having its relay similar to relay PLA¹ picked up, the A line conductor 11 is open at back contact 150 of relay PLA¹ at the station nearest the end of the line.

75 Therefore, only relay LO¹ of Fig. 3 is picked

up during the initiating period and it is stuck up through front contact 193 of relay SA¹ when this latter relay picks up. This stick circuit is closed through front contact 193 before back contact 191 opens. As soon as the relay similar to relay SA¹ at the other station (nearer the control office) picks up, the stick circuit of the relay similar to relay PLA¹ is opened at back contact 193 of the relay similar to relay SA¹. The pick-up circuit of the relay similar to relay PLA¹ is opened at back contact 156 of the relay similar to relay SA¹, so that the relay similar to relay PLA¹ which was picked up at the station nearest the control office is dropped. Other relays similar to relay PLA¹ get their chance to pick up and obtain access to the line during the initiating period of the next cycle, with the station next in order from the end station having preference.

Since the station nearest the end of the line 20 is the only one which can pick up its lock-out relay, this is the only station which can impulse the A and B line conductors in accordance with the connection of the indication buses, because this is the only station with (—) potential connected to the relays PLA¹ and PLB¹ at front contact 199 of relay LO¹. With relays similar to PLA¹ and PLB¹ at all other stations down, the station which obtains access to the line may impulse the A and B conductors, since these circuits are completed at back contacts similar to 30 150 and 153 at all other stations.

Description of modification.—In connection with the transmission of controls, it has been explained that relay FA¹ of Fig. 3 is conditioned to form a portion of the code combinations. Since there are relays similar to relay FA¹ located at all stations in the system and since the A line conductor extends through all of these relays in series, it is evident that they will be conditioned at those stations which are dropped out 40 during the station selection portion of a control cycle. After these stations drop out during the cycle, the contacts of these A line relays are not deenergized at front contacts 177 and 221 of the 45 relays similar to relay SO¹ at those stations which are dropped out of the cycle.

Likewise, during an indication cycle, these A line relays will be intermittently operated, since 50 they are included in the A line return conductor. In this instance their contacts are likewise ineffective to condition any circuits because the station relays similar to relay SO¹ are all down.

In order to prevent the useless intermittent 55 operation of these A line relays, the circuit arrangement of Fig. 5 is provided. During the transmission of controls, the A line impulsing relays such as relays FA¹, FA², FA³, etc., are short circuited at normally closed back contacts of relays SO¹, SO², SO³, etc., at those stations which 60 are dropped out of the cycle. At those stations which remain in connection with the communication system with the station relays (SO) picked up, the A line relays such as FA¹, FA² and FA³ 65 are included in the A line conductor so that they are effective to condition their respective circuits.

In order to equalize the resistance of the A line 70 conductor, resistance coils RS¹, RS², RS³, etc., are included in series with the A line conductor at those stations having the A line relays short circuited. At those stations with the A line relays included in the A line conductor, the respective resistance coils are short circuited so that the 75 resistance of the A line is maintained substantially

constant during all these conditions. It is obvious that the value of each one of these resistance coils will be approximately the same as its associated A line relay.

Having thus described one specific embodiment 5 with one modification of a centralized traffic controlling system, it is to be understood that the particular arrangements illustrated are only typical illustrations of applicant's invention and are not intended to illustrate the exact circuit design 10 necessary to carry out the features of the invention, but have been selected to facilitate in the disclosure rather than to limit its scope and it is further desired to be understood that various modifications may be made and various adaptations and alterations may be applied to the specific form disclosed, in order to meet the various problems encountered in practice and that the system may be varied in the number of field stations to which the invention is applied and the 20 amount of apparatus installed at a particular field station, all without in any manner departing from the spirit or scope of the present invention except as limited by the appended claims.

What I claim is:

1. In a centralized traffic controlling system, a control office, a plurality of field stations, a control line and a plurality of return lines connecting said control office with said field stations, a relay at each of said field stations included in 30 said control line, a relay at each of said field stations included in one of said return lines, means for intermittently energizing said control line by impulses of current applied to said line in series with said return lines in different combinations, 35 means controlled by said relays in combination for selecting one of said field stations, and means for excluding said relays from said return line at stations not selected.

2. In a centralized traffic controlling system, 40 a control office, a plurality of field stations, a control line and a plurality of return lines connecting said control office with said field stations, a relay at each of said field stations included in said control line, a relay at each of said field stations included in one of said return lines, means for intermittently energizing said relays by impulses of current applied to said lines in series 45 in different combinations, for selecting one of said field stations, means for automatically excluding 50 said relays from said one return line at stations not selected, and means for equalizing said one return line relative to the remaining lines.

3. In a centralized traffic controlling system, a control office, a plurality of field stations, a control line and a plurality of return lines connecting said control office with said field stations, a relay at each of said field stations included in said control line, a relay at each of said field stations included in one of said return lines, means for intermittently energizing said control line by impulses of current applied to said line in series with said return lines in different combinations, 60 means controlled by said relays in combination, for selecting one of said field stations, means for automatically excluding said relays from said one return line at stations not selected, and means for compensating for the exclusion of said relays.

4. In a centralized traffic controlling system, a control office, a plurality of field stations, a line 70 circuit connecting said control office with said field stations, selective mechanisms at said office and at said stations operated in synchronism through a cycle of operations by a plurality of time spaced impulses of current applied to said 75

- line circuit, means for transmitting a plurality of series of outbound messages to said field stations over said line circuit during separate operating cycles of said selective mechanisms, means for transmitting a plurality of series in inbound messages to said control office over said line circuit during separate operating cycles of said selective mechanisms, storing means responsive to a plurality of series of outbound and inbound messages simultaneously awaiting transmission, and means responsive to said storing means for allotting said line circuit for the transmission of outbound and inbound series of messages on alternate cycles of operation of said selective mechanisms.
5. In a centralized traffic controlling system for railroads, a control office, a plurality of field stations, a control line wire extending from said control office through said field stations and connected in series with two return wires extending from said control office through said field stations, a polar relay in said control wire at each of said field stations, a neutral relay in one of said return wires at each of said field stations, a resistor in the other of said return wires to compensate for the resistance of said neutral relays in said one return wire, means at said control office for impressing impulses of positive and/or negative impulses on said control wire in series with said other return wire, means at said control office for at times connecting said one return wire to said other return wire at said control office, whereby said return wires form in multiple a return path for said control wire, and means at each of said stations jointly controlled by said polar and neutral relays at that station in accordance with whether an impulse is positive and/or negative and whether or not said one return wire is connected to said other return wire.
40. 6. In a centralized traffic controlling system, a control office, a plurality of field stations, a control line connecting said control office with said field stations and in series with two return lines in multiple connecting said control office and said field stations, a polar relay included in series in said control line at each of said field stations, a neutral relay included in series in one of said return lines at each of said field stations, means in said control office for applying a series of positive and/or negative impulses to said control line in series with said return lines, means in said control office for opening said one return line during selected ones of said impulses, and means at each of said field stations jointly controlled by said polar and neutral relays at that station during said series of impulses for selecting a particular one of said plurality of field stations dependent upon the composite polarity characteristics of said impulses of the series and the selected ones of said impulses during which said one return line circuit is opened.
55. 7. In a centralized traffic controlling system, a control office, a plurality of field stations, a control line in series with a plurality of return lines connecting said control office with said field stations, means at said control office for energizing said control line with a series of distinctive impulses in series with said return lines in multiple, means at said control office for selectively opening only one of said return lines for selected ones of said impulses, a step-by-step means at each of said field stations caused to take one step for each impulse of said series of impulses irrespective of its character, a first relay at each 70 of said field stations included in series in said

control line and responsive to the distinctiveness of said impulses impressed thereon, a second relay at each of said field stations included in series in said one return line and responsive to its opened or closed condition, and means at each 5 station responsive on each step to the composite condition of said first and second relays.

8. In a centralized traffic controlling system, a control office, a plurality of field stations, a control line wire connecting said control office and 10 said field stations, a plurality of return line wires connecting said control office and said field stations, impulsive means effective when initiated for impressing series of impulses on said control line in series with said return lines in multiple 15 to comprise cycles of operation, step-by-step means at said control office and at each of said field stations caused to take one step for each impulse of a series impressed on said control line, code transmitting means at said control office 20 capable when rendered effective to determine on each step the distinctive character of the impulse impressed on said control line for that step and to open or leave closed one of said return line wires for each step all in accordance with 25 a code, code transmitting means at each field station capable when rendered effective to open one or the other of said return line wires on each step in accordance with a code, means for initiating said impulsive means from said control office and each of said field stations, and means rendering only one of said code transmitting means effective during any one cycle of 30 operation.

9. In a centralized traffic controlling system, a control office, a plurality of field stations, a control line wire connecting said control office and said field stations; a plurality of return line wires connecting said control office and said field stations, impulsive means effective when initiated 40 for impressing successive series of a predetermined number of impulses on said control line from a source of current in said control office in series with said return lines in multiple to comprise cycles of operations, step-by-step means 45 at said control office and at each of said field stations caused to take one step for each impulse of a series impressed on said control line, code transmitting means at said control office capable when rendered effective to determine on each 50 step the distinctive character of the impulse impressed on said control line for that step by said impulsive means and to open or leave closed one of said return line wires for each step all in accordance with a code, code transmitting means 55 at each field station capable when rendered effective to open one or the other of said return line wires on each step in accordance with a code, means for initiating said impulsive means from said control office and each of said field stations 60 to cause said impulsive means to be effective irrespective of which of said code transmitting means is effective for any particular cycle, and means rendering said control office code transmitting means and particular ones of said field 65 station code transmitting means alternately effective on succeeding cycles of operation.

10. In a centralized traffic controlling system, a control office, a field station, step-by-step means at said control office and at said field station operable through a predetermined number of steps in synchronism to comprise a cycle of operation, a line circuit connecting said control office and said field station, code transmitting means at said control office capable when rendered effective to 75

condition said line circuit on each step to thereby transmit a code to said field station, code transmitting means at said field station capable when rendered effective to condition said line circuit 5 on each step to thereby transmit a code to said control office, and means rendering said code transmitting means alternately effective on successive cycles of operation.

11. In a centralized traffic controlling system, 10 a control office, a plurality of field stations, a control line and a plurality of return lines connecting said control office with said field stations, a control line relay at each of said field stations included in said control line, a return line relay 15 at each of said field stations included in one of said return lines, means for intermittently energizing said control line by distinctive impulses of current applied to said control line in series with said return lines in different combinations, 20 means controlled by said control and return line relays at a station in accordance with said distinctive impulses and combinations of said return lines for selecting one of said field stations, means at each field station for automatically excluding 25 said return line relay at that station from said one return line when such station fails to be selected, and means for maintaining the impedance of said one return line constant irrespective of the inclusion or exclusion of said 30 return line relays.

12. In a centralized traffic controlling system, 35 a control office, a plurality of field stations, a control line in series with a plurality of return lines connecting said control office with said field stations, means at said control office for energizing said control line in series with said return lines in multiple with a series of distinctive impulses, a station selecting relay at each of said field stations, means responsive to one of said impulses 40 for energizing the station selecting relays at said plurality of field stations, means at said control office for selectively opening one of said return lines for selected ones of said impulses, a step-by-step means at each of said field stations 45 caused to take one step for each impulse of said series of impulses irrespective of its character, a control line relay at each of said field stations included in series in said control line and responsive to the distinctiveness of said impulses im- 50 pressed thereon, a return line relay at each of said field stations included in series in said one return line and responsive to its open or closed condition, and means at each station controlled on each step by the composite condition of said control and return line relays at that station for maintaining said station selecting relay energized 55 during such step only if such composite condition corresponds to the code condition characteristic of that station for that step.

13. In a centralized traffic controlling system, 60 a control office, a plurality of field stations, step-by-step mechanism at said control office and at said field stations having normal positions, means for operating said step-by-step mechanisms from their normal positions through a predetermined 65 number of steps in synchronism back to their normal positions to comprise a cycle of operations, a line circuit connecting said control office and said field stations, code transmitting means at said control office and code transmitting means 70 at said field stations, means including the code transmitting means at said control office for conditioning said line circuit on each step of said mechanisms to thereby transmit a code to said field stations, means including the code trans-

mitting means at each of said field stations for conditioning said line circuit on each step of said mechanisms to thereby transmit a code to said control office, storing means responsive to a plurality of outbound and inbound codes simultaneously awaiting transmission, and means including said storing means for effecting the alternate transmission of outbound and inbound codes for successive cycles of operation, one outbound 5 or inbound code for each cycle. 10

14. In a remote control system; a control office; a field station; a line circuit connecting said control office and said field station; a stepping relay bank at said control office and at said field station operated step-by-step in synchronism for a predetermined number of steps to comprise a cycle of operation; code transmitting means at said control office capable, when initiated and rendered effective, of conditioning said line circuit on each step of a cycle of operation to thereby transmit a message to said field station; manually operable means at said control office for at times initiating said code transmitting means at said control office; code transmitting means at said field station capable, when initiated and rendered effective, of conditioning said line circuit on each step of a cycle of operation to thereby transmit a message to said control office; automatic means for at times initiating said code transmitting means at said field station; and 20 means for rendering said code transmitting means at the control office or said code transmitting means at the field station effective on each step of a cycle of operation in response to an initiation by its respective initiating means, said means 25 rendering said code transmitting means at said control office and at said field station to be effective on alternate cycles of operation when both said code transmitting means are initiated simultaneously. 30

15. In a normally at rest remote control system; a control office; a field station; a line circuit connecting said control office with said field station; transmitting means at said control office for at times conditioning said line circuit to transmit a control code to the field station, transmitting means at the field station for at times conditioning said line circuit to transmit an indication code to said control office, said code transmitting means at said control office and said code 40 transmitting means at said field station requiring a prolonged interval between successive codes to restore such transmitting means to normal before a succeeding code; and means for storing the condition that a plurality of series of control and indication codes are simultaneously ready for transmission, said means causing a control code to be transmitted first and said means thereafter causing indication and control codes to be transmitted alternately over said line circuit with prolonged intervals between such control codes, 45 whereby the system is restored to a normal-at-rest condition between successive codes. 50

16. In a normally at rest remote control system; a control office; a plurality of field stations; 60 a line circuit connecting said control office with said field stations; transmitting means at said control office for at times conditioning said line circuit to transmit a control code to a selected one of said field stations, transmitting means at 65 each field station for at times conditioning said line circuit to transmit an indication code to said control office from its respective field station, said code transmitting means at the control office and said code transmitting means at each field station 70 75

- requiring a prolonged interval between successive codes to restore such transmitting means to normal before a succeeding code; means at each field station effective to allow the operation of a code transmitting means at only one field station at a time when several field stations have indication codes awaiting transmission; means for storing the condition that a plurality of series of control and indication codes are simultaneously ready for transmission, said means causing a control code to be transmitted first and said means thereafter causing indication and control codes to be transmitted alternately over said line circuit with prolonged intervals between such control codes, whereby the system is restored to a normal-at-rest condition between successive codes.
17. In a centralized traffic controlling system; a control office and a field station; a line circuit connecting said control office and said field station; a normally-at-rest selector type code transmitting and receiving means at the control office

and at the field station, of the type wherein the character of the first element of every code designates whether such code is to be transmitted from the control office to the field station or from the field station to the control office; means at the field station for conditioning the line circuit while the system is at rest for initiating the system into operation; control office initiating means at the control office manually conditioned to initiate the operation of the system; field station initiating means at the control office responsive to the conditioning of said line circuit while the system is at rest to initiate operation of the system; means interlocking said control office initiating means and said field station initiating means when both said control office and said field station initiating means are conditioned at the same time so as to cause the character of the first element of each code of a series of codes to be alternately for controls and indications. 5 10 15 20
